UNITED STATES PATENT OFFICE.

JACOB RUPERTUS, OF PHILADELPHIA, PENNSYLVANIA, ASSIGNOR OF ONE-HALF TO THE MERGENTHALER LINOTYPE COMPANY, OF NEW YORK, N. Y.

MACHINE FOR MAKING STEREOTYPE-MATRICES.

SPECIFICATION forming part of Letters Patent No. 541,445, dated June 18, 1895.

Application filed May 4, 1885. Serial No. 164,818. (No model.)

To all whom it may concern:

Be it known that I, JACOB RUPERTUS, a citizen of the United States, residing in the city and county of Philadelphia and State of 5 Pennsylvania, have invented an Improvement in Machines for Making Stereotype-Matrices, of which the following is a specification.

My invention relates to a class of machines employed for making a stereotype matrix 10 without first resort to a composed form made by the ordinary process of setting up type within a printer's chase, about and upon which composed form a matrix is subsequently cast or formed.

15 Heretofore machines of this class have been adapted to form a matrix either by stamping letter dies separately and in succession into matrix material, in such a manner, for instance, as is described in United States Letters Patent No. 20,081, granted April 27, 1858; to J. McElheran; or else by stamping a previously completely composed line of dies into a matrix, in such a manner, for instance, as is set forth in United States Letters Patent 20 No. 52,073, granted January 16, 1866, to J. Paulding. Heretofore also provision has been made for the justification of a composed line of type dies prior to the impression of such line in a matrix, by providing means for wedging apart the devices which carry the dies, as 25 for instance, in United States Letters Patent No. 72,515, granted December 24, 1867, to J. MacNair. Heretofore again in machines containing radially disposed tiers of die arms 30 carrying dies, all of the dies of each of which tiers are provided with the same letter, of which machines the Paulding is a type, provision has been made for arresting at a proper point the descent of the die arms and for 35 aligning such dies as have been dropped to form a composed line, before the line is impressed. Heretofore moreover, in a machine patented December 16, 1879, in and by United States Letters Patent No. 222,642, granted to 40 J. H. Oberly, trustee, upon an application of J. W. Schuckers, which machine is an improvement upon that class of which the Paulding is a type, provision is made for the redistribution in their carrying frame, after being 45 dropped, of particular die arms, by the radial elevation of such arms, without resort to the

partial rotation of the frame described by Paulding, and a separate key is employed in connection with each die arm to bring said arm into action.

55 My invention relates to that class of machines of which the Paulding is a type, and in which tiers of radially disposed die or type arms are contained in a supporting case or frame having a series of separate holders for the die arms, in which provision is made for arresting the descent of the arms at a given point, and for aligning a composed line of types or dies—in which also provision is made for the employment of a type-setter, so called, 60 or, more properly, a key board containing one key for each tier of die arms, which key board is adapted to be advanced by hand so as to bring its keys successively in range to encounter succeeding dies in the tiers,—in which, 65 finally, the matrix is adapted to be raised against the face of the composed line of type dies so as to take the impression of said line,—and my said invention is an improvement upon the said Paulding machine and likewise 70 upon said Schucker's machine.

75 The object of my invention is the production of a machine for making a stereotype matrix in which a greater number of tiers of die arms can be employed, in which the operation 80 of composing the line of dies is more certain and rapid, and in which the impression in the matrix is more accurate than that formed by any machine of this class of which I have knowledge.

85 The above objects I accomplish by mechanism, a good form of a convenient embodiment of which is represented in the accompanying drawings, and described in this specification, the particular subject matter claimed 90 as novel being hereinafter definitely specified.

Generally stated, my invention comprehends improved constructions of the frame work of the machine (which is made semicircular and adapted to contain at least twice as 95 many tiers of die arms as heretofore possible), of the cases for containing the tiers of die arms, of the die arms themselves, of the type-dies, and of the means for securing the retention of the die arms in their elevated positions.

100 It further comprehends a new and useful

key board the respective keys of which control, respectively, all of the die arms in particular tiers of die arms, together with automatic mechanism by means of which the depression of any key in the board is caused to occasion the advance of the key board as an entirety, so as to cause its keys to successively operate upon each one of the die arms in all of the tiers of die arms.

10 It further comprehends an improved mode of applying the type dies to the die arms, and an improved distributing mechanism for simultaneously elevating or redistributing to their normal position such die arms as have 15 been dropped.

It further comprehends improved devices for justifying a composed line of type dies, and the application of such justifying devices to die arms.

20 It further comprehends an improved means for aligning a composed line of type dies, improved justifying contrivances, and improved means for holding down a composed, aligned, and justified line of type dies and for impressing the matrix against said line, together with improved means for advancing or feeding the matrix.

It further comprehends a means for insuring the accurate deposit of a descending type 30 die, and a means for enabling the operator to detect errors in the composed line before the said line is impressed in the matrix.

35 It finally comprehends such a combination and arrangement of the said several novel or improved instrumentalities as will insure their accurate relative operation.

In the accompanying drawings, which represent to given scales hereinafter mentioned, an apparatus and parts thereof embodying 40 my invention, wherever a dotted line is used to indicate a plane of section, such line is provided with arrow heads, the direction of pointing of which indicates the direction in which sight is taken for a sectional view projected on the plane of such dotted line.

45 In all of the figures similar letters of reference indicate corresponding parts.

Figure 1 is a front elevation of my entire machine, all the parts being in the positions 50 which they occupy when at rest and before the machine is operated to bring them into action. Fig. 2 is an end elevation of the entire machine when all its parts are in the positions which they occupy in Fig. 1, sight being taken from the left-hand end of Fig. 1 or in the direction of the arrow thereon. Fig. 3 is a front elevation of one of my die arms, showing the type-die attached. Fig. 4 is a perspective detail of the lower extremity of 55 that end of a die-arm to which a type-die is attached, and also of a type-die detached therefrom, the view being designed to illustrate the mode of attachment of the die to the arm. Figs. 5 and 6 are perspective views 60 of two type-dies inverted, Fig. 5 being a left-handed, and Fig. 6 a right-handed die, the die of Fig. 5, moreover, being of less breadth

than the die of Fig. 6, because bearing a narrower letter than the letter which the die of said Fig. 6 bears. Fig. 7 is a front elevational detail of the matrix-table, of a portion of the base-plate of the machine, of the several devices which effect the clamping or alignment of a composed line of type-dies, and of the devices which actuate the contrivances for justifying and for holding down the line of dies and for elevating the matrix against them, the several parts being represented in the positions which they occupy before they are thrown into action. Fig. 8 is a view similar to Fig. 7 and of the same parts, representing them, however, in the positions which they occupy when in action and during the act of forming the impression of the composed line in the matrix. Fig. 9 is an end, partly-sectional elevational view of the parts represented in Fig. 7, section being taken in the plane of the dotted line 1 1 of said Fig. 7, and all the parts being in the positions which they are therein represented as occupying. Fig. 10 is a transverse vertical sectional elevation of the parts represented in Fig. 7, sight being taken in the plane of the dotted line 2 2 of said Fig. 7. Fig. 11 is a vertical sectional elevational view of the parts represented in Fig. 9, section, being supposed in the plane of the dotted line 1 1 of said Fig. 9. Fig. 12 is a horizontal sectional under plan view of certain of the parts represented in Fig. 9, section being supposed in the plane of the dotted line 2 2 of said Fig. 9. Fig. 13 is a fragmentary front elevational view of certain of the parts represented in Fig. 8 and in the positions which they occupy in said figure, the gate-standard nearest the eye and all of the base-plate in front of said parts being removed. Fig. 14 is a top plan view of the base-plate in the neighborhood of the clamp-slot therein, section being supposed in the plane of the dotted line 3 3 of Fig. 9, and the gate-standards being removed. Fig. 15 is a view of the parts represented in Fig. 14, representing a line of type-dies in the act, so to speak, of being "composed." Fig. 16 is a longitudinal front sectional elevational detail of the parts represented in Fig. 15, section being supposed in the plane of the dotted line 1 1 of said Fig. 15, and the line of type-dies which is shown as being composed occupying a theoretically-exact transverse central line, the clamping-jaws, however, being shown at rest and the followers which operate the justifiers in the normal position. Fig. 17 is a fragmentary side sectional detail of certain of the parts represented in Fig. 16, showing the position in which the right and left handed dies are respectively apt to descend in the forming of a composed line, representing, also, the action of the clamping-jaws as they approach to align said dies. Fig. 18 is a view of the parts represented in Figs. 16 and 17, showing, also, the position of the type-dies when the clamping-jaws have come together to align the dies when the followers have approached to oper-

the triggers, the tier of die-arms exposed being a tier of forty. This view also represents the trigger-lug of the trigger-stem which operates in connection with said tier in its position of rest before action. Fig. 45 is a central sectional fragmentary detailed view representing one of the spring-pulleys which is employed to assist in the return of the distributor to normal position. Fig. 46 is a front elevational view of a modified construction of the distributing mechanism. Fig. 47 is a transverse sectional elevational view of the devices of Fig. 46, section being supposed in the plane of the dotted line 11 of said figure. Fig. 48 is a top plan view of a composed line of type-dies, illustrating the utility of the application to their upper or exposed surfaces of representations of such types or characters as their lower surfaces carry. Fig. 49 is a central vertical transverse sectional elevation through a type-die, illustrating how the representation of characters corresponds with the characters upon the impressing-surface of said die.

25 Of the foregoing views, Figs. 1 and 2 are drawn to the same scale. Figs. 7 to 12, inclusive, and 14 are drawn to a scale which is double that of Figs. 1 and 2. Figs. 13, 15 to 23, inclusive, 28 to 38, inclusive, and 41, 46 and 47 are drawn to the same scale, which is one-half the full size. Figs. 3 to 6, inclusive, 24 to 27, inclusive, and 42 to 45, inclusive, are drawn full sized.

The Framework.

35 In the drawings, A^x, Figs. 1, 2, 7, 8, 9, 10, 11, 14, 15, 19, 20, and 21, is an elongated horizontal base plate from which are erected two semi-circular parallel flat plates of metal, which I term the front frame plate A, and the rear plate A'.

While I specify semi-circular frame plates, it is proper to qualify by saying that so long as the top portion of the said plates is semi-circular or provided with a semi-circular ridge or rest for the distributor, the form of said plates is not of the essence of the invention.

50 B B', Figs. 1, 2, 28, 29, 30, and 41, are respectively a front and a rear series of frame posts, erected respectively from the front and rear frame plates, and extending radially upward and outward from said plates. At their outer extremities the opposite posts of the two series are connected by transverse cross-bars b upon which are mounted grooved pulleys b^x for a purpose explained hereinafter.

C C' are respectively front and rear rods which together constitute a supplementary frame work, and which rise respectively from the extremities of the base plate and connect together circumferentially the outer extremities of the frame posts.

Erected from the base plate within the arch formed by the frame plates are two parallel standards D D' which I term gate standards, and which are respectively provided with ways d d' within which the gate E is

adapted to travel. Transversely across between the standards and longitudinally a certain distance beyond them in both directions, 70 the base plate is slotted out or cut away as at a², to admit of the operation of the various devices for aligning, justifying, and holding down the dies and for impressing the matrix. Depending from the base plate are four bearings F F' F² F³, in which are horizontally journaled the plunger shaft G and the master shaft H, whereof hereinafter.

I, Figs. 1, 2, 7, 8, 9, 10, 11, 13, 16, 17, 18, 22, and 23, is a horizontally disposed cylindriform 80 table which is preferably a shell inclosed at its ends and made in two sections, and the axis of which is concentric with the plunger shaft as shown in Fig. 11. This table is secured both to the base plate and the depending bearings by the screws i, or in any other convenient manner, and serves to sustain the traveling matrix J, which is a strip of any suitable or properly prepared material.

The base plate, frame plates, frame posts, 90 cross bars, supplementary frame work, gate standards, depending bearings, and cylindriform table, together constitute the frame work proper of the entire device.

The Die Arms.

95

K are the die arms, a series of radially disposed tiers of which pass through and are contained, so to speak, by a series of radially disposed die arm cases L corresponding in number to the number of tiers employed and secured between the frame plates of the frame work.

Each die arm is of the form represented in Figs. 3 and 4 and carries a type or die k, Figs. 105 3, 4, 5, and 6, upon the lower or impression surface of which is formed, for purposes of impression, a character or letter.

By reference to Fig. 1 it will be seen that a series of seventy-four tiers of die arms are 110 contained in the machine therein depicted. Each one of these seventy-four tiers is composed of a series of separate and independent die arms averaging in number thirty, although some tiers contain but twenty arms, 115 and some contain forty, the number depending upon the breadth of the die with which the arms of said series of arms are equipped (each die arm of a given tier being provided with the same letter or character), the letter w, for 120 instance, Fig. 6, being of greater width than the letter i, Fig. 5. Each die arm of the series of each tier is aligned from front to back of the machine with every other die arm of said tier, that is to say, sight taken from immediately in front of each tier indicates but a single die arm. Each tier of die arms passes through a separate and independent die arm case.

In the machine of Fig. 1 twenty-six tiers of 130 die arms to the left of the center may be supposed provided with dies bearing an alphabet in upper case, while twenty-six tiers of arms to the right of the center may in like

ate the justifiers and when the plunger has risen to force the matrix against the dies. Fig. 19 is a top plan view similar to Fig. 15, representing, however, a completely composed and justified line of type dies in the positions which they occupy when an impression is taken from them. Figs. 20 and 21 are transverse vertical sectional detail views of certain of the parts represented in Fig. 10, in Fig. 20 a line of type-dies being shown in the act, so to speak, of being "composed," and Fig. 21 representing a completely composed and justified line in the position of the parts when an impression is being taken in the matrix from said line. Fig. 22 is a front elevational fragmentary detail of a part of the cylindriform matrix-table, representing the devices for occasioning the advance of the matrix upon said table. Fig. 23 is a transverse sectional detail through certain of the parts represented in Fig. 22, section being supposed in the plane of the dotted line 1 1 of said Fig. 22. Fig. 24 is a front elevational view of one of the justifying-blanks and its spreading-bar. Figs. 25 and 26 are top plan views of the same, the parts in Fig. 25 being in their normal position or that represented in Fig. 24, while in Fig. 26 the spreading-bar has been advanced in the manner of its advance for justifying. Fig. 27 is a transverse sectional view in the plane of the dotted line 1 1 of Fig. 24. Fig. 28 is a fragmentary front elevational view of the left-hand side of the front frame-plate of the machine, of a part of the keyboard-frame, of a part of the distributor, and of certain of the left-handed tiers of die-arms, certain of the devices for occasioning the advance of the keyboard being also represented. Fig. 29 is an end elevational view of the parts represented in Fig. 28, sight being taken in the direction of the arrow in said Fig. 28, and the parts being represented in the positions which they occupy previous to the operation of composing a line of dies. Fig. 30 is a fragmentary end elevational view of certain of the parts represented in Fig. 29, the key-board, however, being represented in the position which it assumes after it has been advanced to a predetermined extent, a part of said keyboard being also represented in section so as to more clearly illustrate certain of the devices for occasioning its automatic advance. Fig. 31 is a front sectional elevational view through the keyboard-frame, section being supposed in the plane of the dotted line 1 1 of Fig. 29, and the view being especially designed to represent a good form of ratchet-frame and the ratchet-fingers which actuate the same, representation being also made of the contrivances for occasioning the predetermined advance of the keyboard. In this view all the parts are at rest or in the position which they occupy in Figs. 1, 28, and 29. The keyboard-frame and ratchet-frame are, for economy of space, broken into three segments and not represented as a complete or continu-

ous arc. Figs. 32 and 33 are front sectional elevational views through the keyboard, similar to that of Fig. 31, except that in Fig. 32 the ratchet-frame is shown thrown into action by a ratchet-finger controlled by a key in a tier of forty die-arms and in Fig. 33 thrown into action by a ratchet-finger controlled by a key in a tier of twenty die-arms. Each of these views shows only the left-hand end of the frame. Fig. 34 is a top plan sectional detail through certain of the parts represented in Fig. 31, section being supposed in the plane of the dotted line 1 1 in said figure. Fig. 35 is a view similar to Fig. 34, except that it represents the parts in the positions which they occupy in Fig. 33, the plane being that of the dotted line 1 1 of said Fig. 33. Fig. 36 is a front elevational view, similar to that of Fig. 31, of a modified construction of ratchet-frame. Fig. 37 is a fragmentary top plan view of the keyboard in the region of one of the central keys and of a contrivance for securing the return of the key to its normal seat and the stop-pin for arresting the return of the key after its deflection, the ratchet-frame being broken away to exhibit the ratchet-finger therein. Fig. 38 is a vertical sectional rear elevational detail through that portion of the keyboard-frame which is shown in Fig. 37, section being supposed in the plane of the dotted line 1 1 of said Fig. 37. Figs. 39 and 40 are diagrams explanatory of the action of certain keys and parts connected therewith in the release of die-arms respectively in tiers of twenty and of forty. Fig. 41 is a front sectional elevational view through certain of the die-arm cases and tiers of die-arms of my machine, representing the action of the parts which control the said die-arms when in the act of operating for the composition of a line of type-dies, representing, also, partly in dotted lines, the die-arm distributing mechanism both in and out of action. Fig. 42 is a fragmentary sectional top plan view through the two die-arm cases which are represented to the right of the center in Fig. 41, the section being supposed just above the bottoms of the cases, and the two cases being respectively adapted to contain tiers of forty and twenty die-arms. Fig. 43 is a top plan view, partly sectional, of the two die-arm cases represented in Fig. 42, the sections being taken close to the tops of the said cases and through the transverse diaphragms which separate the said cases in the region of the radial grooves with which said diaphragms are provided. In this view the key-stems and their sheaths are represented as broken away to illustrate the disposition of the parts which they would otherwise cover, certain of the triggers and trigger-springs being thus exposed, while certain of said triggers are represented in section. The view also shows a portion of the keyboard-frame. Fig. 44 is a transverse end elevational view into one of the die-arm cases, sight being taken against the face of the comb-spring-plate and against

manner be supposed provided with an alphabet in lower case, with the exception of the end tiers of die arms upon each side which are provided with justifiers. The remaining 5 twenty tiers may be provided with numerals and punctuation marks.

Before the operation of the machine all of the die arms are lifted and retained, by means hereinafter described, in their cases in the position represented in Fig. 1.

Each die arm is preferably formed of a single piece of wire bent upon itself in such manner as to form the inverted elongated U shown in Fig. 3, so that the die arm is in effect longitudinally slotted. One of the ends of said bent wire terminates abruptly at a point above the type die, and a short distance above said end that side of the wire is bent out to form an off-set k^x , or edgewise outwardly projecting portion. The other end of the bent wire is longer and preferably flattened into a yielding or spring-like portion k' , which is at its terminal extremity provided with a cylindriform knob k^2 for attachment to the 25 type die.

The Type Dies.

Each type die k is T shaped, that is to say, formed of a cross-head k^3 and a leg k^4 . The 30 upper and under surfaces of the cross head and under surface of the leg are best all parallel, and the edges of the leg are likewise parallel and best right angular to the under surface of the cross head. The under surface 35 of the leg is provided with the projecting type or character. One of the ends of the cross head terminates in a circular lip k^5 through which is drilled or punched a hole k^6 out from which is radially cut a slot k^7 .

Each type die is connected to its die arm by having the cylindriform knob and the adjacent portion of the yielding end of the die arm respectively entered within the hole and the slot in its circular lip, the fit being snug, 40 and the connection, while permitting of the ready removal of a particular type die, being both cheap and effectual. The side faces of the type dies are parallel and lie in planes parallel and preferably coincident with the 45 planes of the sides of the die arms.

The type dies which are connected with such die arms as are disposed to the right of the center frame posts of my machine, are formed with their circular lips upon the right 50 hand side of their cross heads; while the type dies which are connected with such die arms as are disposed to the left of the center frame posts, are constructed with their circular lips upon the left hand extremities of their cross 55 head, as will be best understood by a reference to Figs. 5, 6, and 41, and I therefore, for convenience, term the type-dies right and left handed dies. Of course all of the types or characters which the respective right and left 60 handed type dies carry face in a common direction, that is to say, in the machine as represented in Fig. 1, with their heads or the up-

per portions of their types to the right hand side of the machine. The object of this construction and mode of application of the dies 70 is to render it possible to use tiers of arms radiating from opposite sides of a central vertical plane, and for the gate to descend alike upon the upper surfaces of the cross heads of all of the dies of a composed line, without 75 possibility of encounter with the die arms, whereby I am enabled to use twice the number of type dies otherwise possible.

All of the type dies, whether right or left handed are of the same depth from top of 80 cross piece to impressing face of type, that is to say, their impressing surfaces, when the type dies are aligned, are in a common plane, which is parallel with the plane of the surface of the base plate of the machine. All of 85 the legs of each of the die arms, whether the latter be right or left handed, are, likewise, of the same breadth from side to side whatever may be their thickness, so that the aligning jaws operate alike upon all of the type 90 dies.

As already stated, the thickness of the type dies varies with the form of the letter or other character which they respectively bear, so that wide letters or numbers are mounted 95 upon thicker type dies than narrow letters or numbers, and, as also stated, in consequence thereof, certain of the tiers of die arms contain a greater number of arms than others;— but, whether the type dies be thick or thin, 100 or right or left handed in the sense already explained, when deposited or composed for impression they are adapted to be compacted, aligned and retained together as a compacted line of composed type dies, which, when 105 viewed from the side, as to their cross heads and legs, present an identical outline. Each type die upon its upper surface or cross head is provided with a representation, facsimile, 110 duplicate, image, or portraiture of any desired character, of the letter type or character with which its under surface or leg is provided, in order that when a line of dies is deposited or composed the operator may by the simple inspection of its upper surface detect 115 any error in the composition. This construction is illustrated in Figs. 48 and 49, and is of material importance.

It is perhaps in point here to state that when I employ the term type dies generically, 120 I include the justifying devices which are, as will be presently understood, germane in many particulars to the type dies.

The Die Arm Cases.

A reference to Figs. 1, 28, and 41, will show that each tier of die arms is disposed radially with respect to the transverse central line of the bed plate, which I term the composition line, and which is parallel with and centrally 130 beneath the bottom of the gate E, and that the descent of any particular die arm, whereof hereinafter, will bring the type die which said arm carries down to said composition line.

Ordinarily, as stated, all of the die arms of all of the tiers are retained in the elevated position shown in Fig. 1. Each tier passes through a separate and independent die arm case, as I term it, suitably constructed and supported conveniently between the front and rear frame plates of the frame work. Each die arm case, being preferably of the construction hereinafter detailed, may be said to radiate from the said composition line; and each die arm case is adapted not only to receive and in a certain sense contain a tier of die arms, but also to contain means for affording such support to each die arm of said tier as is essential to secure the proper transverse and radial alignment of all the die arms composing a given tier, not only when in a position of rest but also in their action of dropping or gravitational descent. Each case also serves to contain the instrumentalities which maintain the die arms in their normal, or elevated positions, as well as the instrumentalities which release given die arms and permit their gravitational descent; and incidentally the cases serve to stiffen the frame plates. Many constructions of the cases as such may be resorted to. I, however, prefer, for reasons of simplicity and economy, to construct the cases in the following manner: A series of sectoral end plates l of a length preferably equal to the depth of the frame plates, and of such proportions as to lie side by side against the inner sides of the frame plates, Figs. 41 and 42, are assembled in segmental relationship and constitute the ends of a given series of cases. These plates are suitably secured, as for instance by bolts as shown in Fig. 42, to the respective frame plates.

Each case is not entirely closed at its sides, but the cases are divided by transverse diaphragms l^2 preferably cast as a part of the sectoral end plates and extending from the top of said end plates to a depth approximately of half of the case. Each opposite pair of sectoral end plates is thus connected by a transverse diaphragm, and is also connected at its base by a bottom plate l^3 and likewise by a transverse bar l^4 to which the comb spring plate l^5 is secured. The diaphragm, bottom plate, and transverse bar of each case are all cast with the two sectoral end plates which form the ends of said case. The diaphragms, therefore, form the sides, so to speak, or divisions between the cases. Each of the two series of cases is conveniently inclosed at its ends by an inclosing plate l^6 , Figs. 29, 30, 41, 42, and 43. All the die arms of each tier are, as stated, placed side by side, and each die arm is astride the diaphragm of the particular case which contains the tier of which it is a member. The striding of the die arms upon the diaphragms serves to assist in maintaining the radial set of each tier of die arms. Each die arm of each tier is, moreover, retained flatwise in parallelism with every other die arm of the same tier, first, by providing the upper edge of each diaphragm

upon its opposite sides with two series of correspondingly opposite radial grooves l^7 , Figs. 41 and 43, which correspond in number with the number of the die arms intended to be contained in a particular case, and which are conveniently formed by forming the upper edge of the diaphragm of considerable thickness and slotting such thickened portion out, and, second, by providing the bottom plates of the cases with a series of radial grooves l^8 corresponding with and aligned below one set of the upper radial grooves in the diaphragm through which grooves l^9 the longer legs of the die arms pass, and with an elongated slot l^{10} in proximity to said series of grooves through which slot the shorter legs of said die arms pass. The conjoint effect, therefore, of the diaphragms, the double sets of radial grooves formed or connected therewith, and the set of radial grooves, and the slot in the bottom plates of the cases, is to secure not only the proper radial disposition of the tiers of die arms but also the proper flat-wise parallelism, so to speak, of all of the die arms in each given tier. The slot l^{10} in each frame plate is long enough to take in the shorter legs of all of the die arms in a particular tier, and broad enough to permit of the free gravitational descent of the die arms notwithstanding the additional thickness which the off-sets l^{11} confer upon said shorter legs.

It will be observed by a reference to Figs. 16, 17, and 18, that when a sufficient number of die arms have descended to form a composed line of type dies, the die arms which are connected with right handed type dies radiate from a different transverse line than that from which radiate the die arms connected with the left handed type-dies, and this is due to the formation of the respective type dies and is designed to permit of the descent of the gate upon all of the respective composed right and left handed type-dies. Now the lines from which the respective right and left handed die arms radiate are respectively the two centers from which the so-called semi-circular or arc-shaped frame plates spring, the said frame plates not being continuous arcs or semi-circles, but being, in fact, two segments which are centrally connected by a straight and not segmental portion. I deem it proper to mention the above fact, so that it may be understood why the die arms do not in fact descend to a common center. When the die arms are elevated or in a position of rest, the type dies are exposed a little below the frame plates of the cases, while the upper extremities of the arms extend to a considerable distance above the cases, as shown in Fig. 1.

The projection of the die arms above the cases is such as to allow of a sufficient descent to bring the type dies into horizontal coincidence with the composition line at the base plate. The radial distance to which the type dies must be elevated is determined, measurably, by the shape of the type dies themselves,

and the extent of radial elevation is such that when all of the dies are elevated they clear one another as shown in Figs. 1 and 41.

5 *The Triggers Controlling the Die Arms.*

The bottom edge of each diaphragm is provided with a series of parallel radial equi-distant ribs b^6 , preferably made by slotting, the slotted grooves or spaces between which are 10 aligned below the grooves b^6 of said diaphragm, and serve to permit the passage of the shorter legs of the die arms. The office of these ribs is to serve as supports for the fulcra of a set of triggers c , Figs. 41, 43, and 44, one of which 15 triggers is placed in the groove between each adjacent pair of ribs b^6 , and all of which are fulcrumed upon a rod or wire c^2 which preferably is continuous through all of the ribs b^6 .

The triggers are levers of the first order and 20 fulcrumed at about their centers. The lower arm of each trigger is controlled by a spring b^8 , Figs. 41, 43, and 44, all of the springs being preferably formed as a single comb spring plate, as will be best understood by a reference 25 to Fig. 44.

The normal or elevated set of the die arms, Fig. 41, is maintained by the frictional contact of the lower arm of the triggers with the off-sets k^x of the die arms, the said contact 30 being due to the stress of the springs, which is constant.

It is obvious that a deflection of the upper end of a trigger against the resistance of its spring by a force sufficient to overcome said 35 resistance and deflect the lower end of the trigger, will permit the release of the die arm controlled by said trigger, and, as there is no other opposing instrumentality, its full gravitational radial descent.

40 The devices which occasion the above deflection of the triggers are connected with and controlled by the keys of the machine, and will be presently described.

The end of each trigger is provided with an 45 overhanging stop c^3 which, after the descent of a particular arm, as shown in Figs. 41 and 43, prevents by contact with the radial rib which is adjacent to it, the deflection of said lower end of the trigger by its spring to an 50 extent sufficient to cause said trigger to bind against the die arm and so arrest its descent.

The purpose of forming the off-set on the die arms is, more particularly, to permit of the quick release of a die arm when a key is 55 touched, and avoid the necessity of maintaining the key depressed until the released die arm has completed its descent, and the overhanging stop upon the triggers contributes to the above result by preventing the triggers 60 from impinging against the leg of the die arms except at the off set.

The Finger Keys.

Transversely across the top of each die arm 65 case is inserted and fixed a tubular sheath c^4 , Figs. 41, 43, and 44, the chief office of which is to serve as a slide bearing for the key stems.

The form of these tubular sheaths is best shown in Figs 41 and 44, and they are bottomless, so to speak, in order to permit the 70 longitudinal travel and rotative throw of the trigger lugs c^5 which are mounted upon the key stems m .

M are the keys, disposed in the arc of a circle in an assemblage constituting, in popular 75 phrase, the key board of the machine. These keys are provided upon their finger portions with letters or characters corresponding to the letters or characters with which the respective tiers of the type dies of the die arms 80 are provided. Each key is a lever and is mounted upon a particular key stem which passes through a particular die arm case and is housed therein in the tubular sheath thereof.

Reference to Figs. 1, 28, 29, 30, and 43, will indicate that the keys are disposed in a segmental nest so to speak, or rather in two nests respectively right and left handed, each key of each nest inclining toward its neighbor 90 and presenting its finger portion approximately level to the pressure of the fingers. Normally the keys stand in such inclination that their finger portions present a continuous 95 arc, as shown in Figs. 1, 28, and 29. Depression of a particular key throws its finger portion out of the line of this arc, while upon its release it is controlled, as hereinafter explained, to instantly resume its former position.

100 Each key, through the instrumentality of its stem, is adapted to control all of the die arms in a particular tier, and this is accomplished by virtue of a trigger lug c^5 with which each key stem is provided, and which is in 105 range for an engagement controllable by the key, with the upper end of any particular trigger in a given case opposite which trigger the said trigger lug is for the time being caused to stand.

110 For better explanation, I would here state that the line of type dies which it is desired to set up is composed from the rear to the front of the machine and along what I have termed the composition line of the base plate, 115 and that the die arms are selected and dropped from the rear of the tiers forward to the front.

The Key Board Frame.

Now as each die arm case is provided with 120 its own key stem operated by a particular key, and as each stem has but a single trigger lug, it is obvious that, if the said trigger lug is to do duty in controlling the release of all of the die arms in a particular case, it will 125 be necessary to provide means for securing the uniform but intermittent simultaneous advance from the rear to the front of all of the said cases of all of said trigger lugs and the said key stems which carry them, so that the 130 said trigger lugs may intermittently but successively face and be in range for engagement with each one of the triggers in the said cases. This is accomplished by mounting all of the

keys and their connected key stems, in a key board frame, herein sometimes termed the key board, which is adapted intermittently but constantly under the actuation of any 5 one of the keys to advance from a rearmost normal position at starting (forward) to an extent sufficient to cause the sweep or advance of all of the trigger lugs throughout the entire length or depth, so to speak, of the cases, 10 and past each trigger,—it being borne in mind, of course, that the key stems pass completely “fore and aft,” so to speak, through the cases and that in their position of rest before starting they are preferably of such length as to 15 project to the rear of the cases to a considerable extent, as shown in Figs. 2 and 29.

The key board frame is preferably composed of two upright parallel arc-shaped segmental plates N N' Figs. 28, 29, 30, and 43, 20 which are connected together at their extremities and at the center by tubular boxings n, the two end boxings being respectively mounted and free to travel in and out upon horizontal studs n² secured to the frame plates 25 and projecting to the front therefrom. The segmental plates N N' are parallel with and stand immediately in front of the frame plates A A'. The stems of the keys pass through and journal in the said segmental plates as 30 shown in Fig. 43, and it is obvious that, when the said key board frame is moved in and out upon the studs on which it travels, the key stems and keys move in and out with it, and that therefore whatever in and out 35 movement is imparted to it is likewise imparted to the said keys and stems.

When the machine is in the position represented in Fig. 1 and ready to be operated upon, the key board frame is in the position 40 represented in Figs. 29 and 43, that is to say in to the full extent of its movement upon its studs. In this position the trigger lugs upon the key stems are slightly to the rear of the rearmost triggers of each tier of triggers, 45 as shown in Fig. 44.

The Ratchet Frame.

Now it is necessary that the depression of any key in the key board should occasion two 50 results: first, the advance of the key board, keys and stems, and trigger lugs, to an extent sufficient to bring the trigger lugs in front of the rearmost triggers, and, second, the deflection of the trigger which the trigger lug 55 of the key depressed is caused to face, so that a type die and die arm of the tier of the key struck may be released and descend. The second of the above results is accomplished by the completion of the rotation of the stem 60 of the key depressed, the final rotation of said stem causing the trigger lug with which it is equipped to deflect the trigger it is caused to face, as one of the lugs is shown as doing in Fig. 41; but the first above result, of occasion- 65 ing a predetermined advance of the key board, keys, and stems, is accomplished through the instrumentality or intervention of what I

term a ratchet frame O, Figs. 29, 30, 31, 32, 33, 34, and 35, the same being a segmental plate of approximately the same dimensions 70 and of the same curvature as the segmental plates of the key board frame, which is mounted and supported between the said plates upon a ratchet shaft P Figs. 1, 28, 29, 30, 31, 32, 33, 34, and 35, upon which it is supported, conveniently through the intervention of the grooved wheels o', so as to be capable of a limited end for end travel thereupon. Support is also afforded for the said ratchet frame by a transverse web o², Figs. 31, 36, and 80 43, which covers and has a movement over the central tubular boxing n of the key board frame. At its lower, and in the apparatus shown, left hand extremity, the said ratchet frame is provided with a pivoted pawl o³, Figs. 85 28, 29, 30, 31, 32, 33, 34, and 35, which on its under surface is provided with an angularly disposed tooth o⁴ adapted to engage with the angular teeth of a ratchet wheel p mounted upon the extremity of the ratchet shaft P. 90 The pawl is controlled in such manner that its tooth is normally in bite with the teeth of the ratchet wheel by a spring o⁵ coiled about its pivot pin o⁶ and bearing as to its operating extremity upon the pawl near its handle 95 o⁷. The pivot pin of the pawl is housed in a suitable bearing formed in the extremity of the ratchet frame, the said frame being conveniently bent over upon itself as shown in Figs. 28, 30, 31, 32, 33, 34, and 35, not only for 100 the purpose of forming bearings for the pivot and grooved wheel o', but to form a sleeve o⁸ for encircling the ratchet shaft P. Both ends of the ratchet frame are bent over to form the sleeves for the said shaft, but one extremity 105 only is shown as provided with the pivoted spring-controlled pawl. The ratchet shaft has its bearings in the two lateral tubular boxings n by means of which the key board frame has its in and out movement, and the 110 said boxings are slotted to contain toothed spur wheels p', which are fixedly mounted upon the said ratchet shaft, and are respectively in engagement with racks p² let into the 115 horizontal studs n², as particularly illustrated in Figs. 29, 30, 31, 32, and 33.

Interposed between the inner face of the tubular boxings n, and the exterior face of the sleeve o⁸ formed upon the left hand extremity of the ratchet frame, is a spring p³ 120 coiled upon the ratchet shaft, the office of which is to throw to the right hand or return the ratchet frame after it has been moved laterally to the left hand, as hereinafter explained.

Now it is obvious that, if a movement be imparted to the ratchet frame from the right to the left hand of the machine, the tooth of the pivoted pawl which is in engagement with the ratchet wheel will occasion a predetermined backward rotation of said ratchet wheel, and consequently a corresponding rotation in the ratchet shaft and the toothed spur wheels with which said shaft is equipped,

the coiled spring p^3 being compressed, with the result that, by reason of the engagement of said spur wheels with the racks upon the horizontal studs n^2 a predetermined advance 5 of the key board frame work will be secured;— that so soon as the force which is employed to move the said ratchet frame from the right to the left, ceases to exert itself, the expansion of the spring p^3 will serve to return the 10 said ratchet frame from the left to the right, the toothed spring pawl during such return rising out of the teeth of the ratchet wheel with which it has been engaged, the said wheel, by reason of the weight and inertia of 15 the key board frame and connections as an entirety, remaining at rest, but, after the completion of the throw of the frame under the stress of its pawl spring, re-engaging with another tooth of the said ratchet wheel. The 20 above throw of the ratchet frame, it will therefore be seen occasions a predetermined outward movement of the key board frame, ratchet frame, and connected devices, and of the keys and stems. This predetermined ad- 25 vance is calculated, by the inclination of the teeth of the pivoted pawl and ratchet wheel, to be such as to occasion an advance in the key stems and the trigger lugs sufficient to cause all of the trigger lugs to face either, at 30 the first movement, the rearmost triggers in the die cases, or, at subsequent movements, triggers in advance of those which the said lugs immediately before said movement faced or were in range to act upon.

35 *The Ratchet Fingers.*

The means which I adopt for securing the throw of the ratchet frame from the right to the left hand, are a series of ratchet fingers 40 m^x , one of which is secured to each key stem at a position necessary to cause them to bear against suitably formed abutments m^2 formed in or applied to the ratchet frame.

The ratchet fingers may be of varying form 45 and length, and are shown in Figs. 31, 32, and 33 as acting upon abutments shaped in the substance of the ratchet frame itself, as a reference to the said figures will make clear, and the set of said ratchet fingers upon the key 50 stems is intentionally such that the very first movement of depression of a particular key causes the ratchet finger of the key stem of said key at once to act upon an abutment of the ratchet frame, so that the right to left throw of said frame is accomplished before 55 the trigger lug upon the said key stem acts upon the trigger with which, for the time being, it happens to register.

It is obvious that the abutments, so called, 60 are simply points of resistance upon the ratchet frame, against which the fingers may bear, and that it is inconsequential whether the said abutments be formed in the frame itself, as represented in Figs. 31, 32, and 33, 65 or be simply stop pins m^2 or other resisting media, applied to the said ratchet frame, as shown in Fig. 36.

In either of the foregoing constructions, or in any analogous construction, it is of course necessary that the key stems should either 70 actually or in effect pass through the ratchet frame, and that the ratchet frame should be sufficiently slotted to permit of its free movement from right to left without encounter against any other stem or finger than that the 75 operation of which is occasioning the then movement of said ratchet frame, as a reference to Figs. 31, 32, 33, and 36, will make clear. The return rotation of the key stems and consequent return of the keys to normal position 80 is best accomplished by the application of what I term a key spring m^3 , which is coiled about and connected with the key stem, and also secured to a fixed point upon, for instance, the front segmental plate N of the 85 key board frame as shown in Figs. 37 and 38. It will also be observed that in a machine constructed in exact accordance with that shown in these drawings, the trigger springs t^5 exert, upon the relief of pressure by the 90 trigger lug upon the trigger, a sufficient influence in deflecting the trigger to the extent that its overhanging stop c^3 will permit, to occasion a reverse throw by the trigger of the trigger lug and key stem, and so to bring the 95 ratchet finger of the stem under consideration into a position in which the recoil of the ratchet finger of the stem under consideration into a position in which the recoil of the 100 spring p^3 on the ratchet frame acting through said frame and its abutment upon said finger, will occasion the complete return rotation 105 of said key stem and the return of the connected key to its normal position. Of course, in a position of rest before action, the ratchet frame under the influence of the spring p^3 stands to the right to the full extent of its 110 movement in that direction, as shown in Fig. 31, and in this position, its throw being limited by a collar p^4 upon the ratchet shaft P against which collar the sleeve o^3 on that end of the frame abuts, each ratchet finger is in bite, so to 115 speak, against its abutment, so that the depression of a key instantly occasions the movement of said ratchet frame to the left hand. It will also now be apparent how a single key and a single key stem having but a single trigger lug, is made to do duty to control 120 the drop of any one of the die arms contained in a given tier of die arms in a given case; and also how the predetermined intermittent advance of the key board frame work, ratchet 125 frame, keys, and stems,—occasioned, as already explained, through the movement of any key,—is the means by which a trigger lug on an intermittently advancing key stem is caused, step by step so to speak, to force, and, 130 if desired, control the drop of each one of the die arms in the tier which it controls.

The employment of two racks in the studs, and of two spur wheels mounted upon the same shaft, insures the simultaneous and 130 even advance of the key board frame, and prevents any warping or twisting of the latter and any consequent binding upon the studs on which it travels. The key board,

after having been advanced by the play of the keys to the full extent of its forward movement, can be returned either by hand, the spring pawl being, of course, lifted and held 5 out of engagement with the ratchet wheel; by a spring connected with it and with a fixed part of the frame work; or, if desired, by a counterweight, or kindred contrivance, as will be obvious to any mechanic.

10 I have already mentioned that some of the type dies are of greater breadth than others because some letters are broader than others. As, however, each tier of die arms is of the same depth as every other tier, it is obvious 15 that some tiers will contain a greater number of die arms and type dies than others. In the drawings I have represented the tiers as respectively containing, in some instances, twenty, and, in other instances, forty die 20 arms and dies. Now, as all of the trigger lugs are placed at a corresponding point upon their respective stems, it is obvious that those lugs which actuate the triggers controlling the thinner dies must be no broader than 25 the breadth of a single trigger applied in connection with a die arm in a tier of forty die arms, as otherwise such a broad lug would, upon the rotation of its stem, operate upon two triggers simultaneously, and so release 30 two die arms. I have, therefore, made the trigger lugs upon the key stems of keys controlling tiers of forty die arms of the breadth of a single trigger in such tier, while I have made the lugs which control the triggers of 35 tiers of twenty die arms of twice the breadth of the lugs of triggers of tiers of forty, as well as of twice the breadth of the triggers in tiers of twenty. Now it will be readily perceived that, all the triggers being of the same breadth, 40 a broad trigger lug controlling a tier of twenty die arms must, in order to actuate a trigger next in advance of that trigger upon which I suppose its action of trigger-release to commence, advance twice the distance, in the outward movement of the key board, that a trigger lug in a tier of forty die arms must advance 45 for a kindred purpose; and it will therefore be apparent, as a given advance of the key board occasions an equal advance in all the key stems, that such advance as brings a broad lug to bear against a trigger in advance of that trigger which the said lug immediately before presented against, will occasion a co-extensive advance of a narrow lug, or, in other 50 words, such an advance of said narrow lug as will occasion it to skip one of the triggers which it might otherwise control; whereas, upon the contrary, such an advance of the key board as will occasion a narrow lug to 55 move from a given trigger in a tier of forty to the next trigger in advance, will occasion a co-extensive advance in a broad trigger lug, or an advance not equal to the full distance (from center to center) of adjacent triggers 60 in a tier of twenty. As, however, in a tier of forty a predetermined advance of a narrow lug occasioned by its own key, will also bring

the said lug into range with a given trigger next in advance of that last acted upon, and as the same extent of advance of a broad lug 70 will bring the latter by reason of its breadth into position to control a next in advance trigger in a tier of twenty, it is obvious that it is immaterial as to the control of all of the keys upon the particular tier of die arms with 75 which they happen to be connected, whether the advance of the key board be co-extensive with the distance apart of adjacent die arms in tiers of forty, or co-extensive with the distance apart of adjacent die arms in tiers of 80 twenty, inasmuch as, in either case, the trigger lug of a given key, be it a narrow or a broad lug, will always be in range to engage one trigger only of the tier with respect to which it operates. Now, as it is necessary that the 85 broad trigger lugs which control tiers of twenty, should advance, upon each depression of the key controlling them, the full distance apart of the die arms in said tiers of twenty, it is obvious that provision must be made for 90 advancing the key board frame upon the deflection of such a key, twice the distance that it is necessary to advance said key board upon the deflection of a key controlling a trigger in a tier of forty. Such result I accomplish 95 by providing the key stems which control tiers of twenty with ratchet fingers of greater length than the length of the fingers of stems controlling tiers of forty, as a reference to Figs. 31, 32, 33, and 36, will show, the said 100 longer fingers being adapted to bear against abutments of suitably conformed outline to occasion a throw of the ratchet frame from right to left of twice the horizontal distance which it is necessary to throw said frame in 105 order to occasion the advance of the key board to a horizontal distance corresponding with the distance apart of triggers in tiers of forty and of twice the longitudinal extent to which it is thrown by the shorter ratchet fingers, which, as stated, are shown connected 110 with the key stems controlling tiers of forty. To further illustrate, in Fig. 32 a key stem controlling a tier of forty, provided with a narrow trigger lug and with a short ratchet 115 finger, is shown as having been operated, by the depression of the key connected with its stem, to have thrown the ratchet frame to the left to an extent which is approximately equal to, for instance, half the breadth of the toothed 120 face of the ratchet wheel,—the throw in consequence having resulted in such a rotation of the said ratchet wheel and its connected spur wheels as to have caused simply such sufficient advance of the key board frame as to 125 have occasioned the advance of the narrow trigger lug of the stem in question from one trigger to the next trigger in advance in the tier of forty in which said trigger plays. In Fig. 33, on the other hand, a long ratchet finger 130 connected with a key stem having a broad trigger lug and controlling a tier of twenty, is shown as having, upon the deflection of the key connected with its stem, moved the ratchet

frame to the left a horizontal distance which is approximately equal to the full breadth of the toothed face of the ratchet wheel, and which is twice as great as the horizontal movement represented in Fig. 32 as having been imparted,—the said horizontal advance shown in said Fig. 33 having occasioned a rotation of the ratchet wheel twice as great as that supposed occasioned by the movement represented in Fig. 32, and having consequently occasioned, through the toothed spur wheel and rack, an advance of the key board frame of twice the extent of that occasioned by the movement of the ratchet frame illustrated in said Fig. 32. It is obvious, therefore, that it is simply necessary to provide the key stems which control tiers of twenty and have broad trigger lugs, with longer ratchet fingers than the key stems which control tiers of forty and have narrow trigger lugs, and to so conform the abutments of the ratchet frame as to give full effect to the movement which the respective lengths of the said fingers are designed to accomplish,—in order to secure upon the movement of particular keys such predetermined advance in the key board frame as shall insure the accurate operation of the trigger lugs upon the triggers of the tiers which said keys respectively control.

Of course, when a key controlling the die arms in a tier of forty is struck it is immaterial whether a narrow trigger lug skip a given trigger in the tier in question, as, when it stops after such skipping, it stops in front of a trigger which controls a die arm carrying identically the same die as that of the die arm which it skipped; while it is also equally immaterial whether the advance of a broad lug controlling the triggers in a tier of twenty, be its own full breadth and equal to the distance apart of the triggers in such tier, or whether it is simply half such distance, because its own breadth is such that in whatever position it stops it presents against a trigger which controls a die arm in the tier in question next in advance of that which was last in range of the operation of said trigger lug. When, however, it is desired to repeat in succession two, three, or more characters with which the type dies in a given tier of twenty are provided, the key controlling the selected tier is successively struck the desired number of times, each time with the result of occasioning an advance of the key board sufficient to bring forward the broad trigger lug of the key struck to the extent of its full breadth, so that it successively presents against immediately succeeding triggers controlling immediately succeeding die arms in the tier of twenty in question. The advance of a broad trigger lug to the extent of but half its full breadth is only occasioned when a key controlling die arms in a tier of forty is struck, as is done when it is desired to bring one or more of the narrow characters into action. When, on the other hand, it is desired to successively repeat a narrow character, a key

controlling a tier of forty is necessarily the key struck, and its stroke, as already fully explained, while occasioning the advance of its narrow trigger lug to the extent of its full breadth, incidentally occasions an advance of all the broad lugs equal only to half their breadth; while, conversely, as stated, the touch of a key controlling a tier of twenty, occasions an advance of all of the broad trigger lugs equal to their full breadth, and incidentally an advance of all the narrow trigger lugs equal to twice their breadth.

To still further illustrate I have in Figs. 39 and 40 represented, as far as is possible by diagrammatic plans, the above described construction and operation. In these figures the die arms K are indicated by the black disks, and the triggers c by the solid black parallelograms, while the broad trigger lugs are lettered "a" and the narrow trigger lugs a^x . The left hand tier of die arms in each diagram is a tier of forty and the right hand a tier of twenty. In Fig. 39, the trigger lugs a and a^x as indicated by the cross-sectionally lined parallelograms, are both to the extreme rear of the tiers which they respectively control, and this is the position the lugs take before the key board is operated upon. When then the key controlling the narrow lug a^x is first depressed, that lug will advance to the position indicated by the full lined parallelogram a^x , while the broad lug by the same advance of the key board will be caused to assume the position indicated by the full lined parallelogram a, its advance being but one-half its own breadth, although, as shown, sufficient to bring it opposite the first trigger in its tier. Assume now that the key controlling the broad lug is next depressed. The said broad lug will advance from the position indicated by the full lined parallelogram a to that indicated by the dotted lined parallelogram a^x , or its full breadth, and sufficiently far to be in range to engage the trigger next in advance, while at the same time the advance of the key board will have occasioned the advance of the narrow lug a^x in the tier of forty, to the position indicated by the dotted parallelogram a^x representing said lug. In Fig. 40 the lugs are represented by the cross-sectionally lined parallelograms a a^x as, before their advance, in the same position that they at such time occupy in Fig. 39. In this figure, however, the full lined parallelogram a indicates the advance of the broad lug, which is assumed to be first operated, so that said lug is in range for operation upon the first trigger of the tier of twenty, while the full lined parallelogram a^x which indicates the narrow lug, shows how, by the said advance of the broad lug, the narrow lug has been caused to skip the first trigger and to register in front of the second trigger of the tier of forty. The dotted lined parallelogram a^x which indicates the narrow lug, shows the position of said lug when the latter is next operated, and shows that its advance has been

simply its own breadth or from the second trigger to the third, while the dotted lined parallelogram α which indicates the third position of the broad lug shows how the latter, 5 simultaneously with the last mentioned advance of the narrow lug has advanced but one half of its breadth.

The extent of advance of the key board frame occasioned primarily by the impulse 10 and movement given to the ratchet frame by the ratchet fingers, is fixed and determined not only by the length of the fingers and the character of their abutments, but also by the proportions of the ratchet wheel and the pitch 15 and number of its teeth, by the pitch and length of the teeth on the pawl, and by the diameter of the toothed spur wheels, the number of their teeth, and of those of the racks with which they engage,—all matters of me- 20 chanical construction and adaptation which a skilled workman will readily comprehend, and an operative embodiment of which is represented in the drawings forming a part of this specification.

25 I have elected to represent and consider tiers of die arms respectively containing twenty and forty arms, and this I have done for simplicity of representation and explanation. It is obvious, however, that, under suitable modifications, the tiers may be made to contain other numbers of die arms than twenty and forty. Thus one tier might contain thirty, and another sixty, or one ten and another twenty, or by proportioning the various parts 30 which occasion the predetermined advances of the key board and control the retention in their elevated positions of the die arms, the tiers may be made to contain die arms varying in number and not bearing the relation 35 simply of two to one. Thus one tier might be made to contain ten die arms, another twenty, and another forty, without departure from the principles of construction and operation already at length set forth.

40 *The Distributer.*

Having now described the means for securing the retention of the die arms and dies in their elevated position, and also the means 45 for at will securing the radial gravitational descent of any one of the die arms so that its die forms one of the line of dies being composed, it is obvious that means must be provided for the subsequent elevation or lifting 50 of each one of the dies being a member of a given line of composed dies, and the means which I have devised are the following:

55 Q is a series of levers, Figs. 1, 2, 28, and 41, compounded and connected together substantially after the manner of construction resorted to in forming what is known as a "lazy-tongs." Each lever is connected to its neighbor at top and bottom by the pivots q , while centrally-overlapping levers are connected by pivots, which I term lifting bars q^x . 60 There are two parallel sets of these lazy-tongs, or compounded levers, each of which as a

whole is arc-shaped. Through the medium of lever sleeves q^2 to which certain of said levers of each set are at intervals connected, 70 the two lazy tongs are mounted to slide upon the frame posts of the frame work, one of them being by such means mounted, so to speak, or superimposed upon the front frame plate, and the other upon the rear frame plate. 75 Each lazy tongs is provided with its own lever sleeves, of which those connected with the front lazy tongs ride upon the front frame posts and those connected with the rear lazy tongs upon the rear frame posts. The two 80 lazy tongs are, by means of the lifting bars which pass transversely and horizontally from the central point of given levers in the front lazy tongs to a corresponding central point in corresponding levers in the rear lazy tongs, 85 connected so as together to form a composite device which, in connection with the cords which control its upward movement, is herein termed the distributor or distributing apparatus.

90 Each of the lifting bars q^x passes completely through a particular tier of die arms. The die arms, as a reference to Fig. 3 will show, have between their legs a longitudinal slot or space which amounts in effect to a continuous 95 slot through the center of all the die arms of a given tier, and is of the length of said arms.

99 The sleeves of the respective lazy tongs may, if desired, be connected by cord bars q^3 , Figs. 29 and 30, which may or may not, as convenience of manufacture may dictate, be pivots of given levers of the respective lazy tongs. I prefer, however, that these cord bars should be upper pivots of particular levers of the respective lazy tongs, as in Figs. 29, 30, and 41, 100 they are represented as being. The office of these cord bars is to serve as points of attachment for the cords q^4 by means of which the two lazy-tongs and their connected sleeves are raised to secure the elevation of the die arms, 105 as shown in dotted lines in Fig. 41. A convenient arrangement of these cords is that shown in Figs. 1, 2, 29, and 41, in which six 110 separate cords are employed, which are respectively connected, two of them to the central cord bars connecting the two central sleeves, and one to each of the four lateral cord bars which connect respectively the end and the intermediate sleeves. The grooved pulleys b^x which, as already stated, are 115 mounted upon the cross bars b of the supplementary frame work, receive and carry these cords. The central pulley has five grooves, the two intermediate pulleys have each two 120 grooves, and the end pulleys have each one groove. The outside cords, or those connected with the cord bars of the end sleeves, pass first over the end pulleys which have but a single groove, and then over the intermediate pulleys which have two grooves, and then in 125 opposite directions around the central pulley which has five grooves. The cords connected with the cord bars of the intermediate sleeves, 130 pass over the other groove of the intermedi-

ate pulleys, and then in opposite directions around separate grooves in the middle pulley. All of the cords are then above said middle pulley connected at the same point with a 5 pull cord q^5 which is, by being carried around a pulley, not shown, placed within reach of the operator.

Ordinarily the distributor as an entirety rests by its respective lazy-tongs upon the 10 respective frame plates of the machine, or upon ribs or rests either secured thereon or otherwise applied. In this position, as already stated, all of the die arms in given series span, stride, or bridge the lifting bars q^6 of 15 said lazy tongs, which in the set of the distributor must each occupy a position correspondent with the radial axis of a given tier of die arms.

When a particular die arm is operated to 20 be dropped, its descent continues until arrested by the contact of its upper looped extremity with the lifting bar which passes through it.

When a line of dies has been composed by 25 the descent of the required number of die arms, all of the descended arms will be suspended so as to speak upon the lifting bars which pass through them. After the line has been impressed into the matrix, it is desirable 30 to raise all of the arms simultaneously, and this is accomplished, as already indicated, by a pull upon the pull cord, which, operating through its connected cords, causes the unfolding, so to speak, and lifting of the two 35 lazy tongs from their folded lower position. Shown in Figs. 1 and 28 and in full lines in Fig. 41. In this unfolding and lifting of the two lazy-tongs, it is of course essential that the lifting bars should respectively travel in 40 planes coincident with the radial axes of the respective tiers of die arms, as, were their movement not coincident with such axes, the deflection and consequent retention of the die arms would necessarily result. This desideratum I accomplish by forming each lever of 45 the two lazy tongs upon a slight curve, as clearly shown in Figs. 28 and 41, the said curve being correspondent to the curve or arc of the frame plates, and having about the 50 same radius as that of the peripheral edge of said frame plates. The object therefore of making these levers slightly curved, is not because a curved lever as such is better than a straight lever, but because it is desirable 55 that the three holes for the three pivots of each lever should be upon an arc the radius of which is as stated about that of the peripheral edge of a frame plate, and because it is easier to center the said holes when the 60 lever is itself curved. The curves of the respective levers are, in the set up of each lazy-tongs, reversed, as a reference to the drawings will make clear.

It will now be understood in what manner 65 the lifting of the two lazy tongs occasions the

simultaneous elevation of any line or series of descended die arms.

After the elevation of the two lazy tongs by their common cord, their tendency, upon the 70 release of the cord, is to gravitate again to their normal position above the peripheral edges of the frame plates; and, were the tongs retained in their elevated positions, the then positions of their lifting bars would prevent 75 the descent of any of the die arms.

To guard against any possible failure of the 80 lazy tongs to gravitate to a normal position, I have provided the following device for insuring with certainty their prompt return.

q^6 is an axial stud, which is represented in Figs. 2, 29, 30, and 45, screwed into the outside face of the outside inclosing plate l^x upon one end of one series of die arm cases. Upon this stud is mounted free for revolution a shell 85 like grooved spring pulley q^7 , to which is connected and upon which is adapted to be wound a cord q^8 which is carried up and connected to the end cord bar of the tongs which is above said pulley. Within the hollow interior of 90 the spring pulley is a coiled band spring q' , one extremity of which is rigidly connected with the inclosing plate l^x , or, as shown in Fig. 45, with an adjustable washer centered upon the stud and adapted to be bound by it 95 fixedly in given positions against the outside face of the inclosing plate,—and the other extremity of which is fixedly connected with the pulley.

When the distributor is down the cord q^8 is 100 wound upon the pulley and the spring unwound. Upon the lifting of the distributor the cord is unwound from the pulley, and, in the act of unwinding, the spring wound, so that upon the release of the two lazy tongs 105 the spring uncoiling acts to rewind the cord upon the pulley, and insures traction downwardly upon the distributor as an entirety. One of these spring pulleys is applied to each 110 end inclosing plate, so as to equalize the action upon the distributor. This device is in the nature of a safeguard and is not indispensable, as the weight of the two lazy tongs under ordinary conditions insures the return 115 of the distributor to normal position.

In order to guard against any possible want of parallelism between the radial planes of movement of the lifting bars of the two lazy tongs, and the radial axial planes of the tiers of die arms, as hereinbefore mentioned, I 120 have in Figs. 46 and 47 illustrated a mechanical modification by which the inner lifting bars are not the central pivots of the levers of the respective lazy tongs, but are suspended by swinging stirrups q^9 from central 125 pivots q^{10} which do not extend across from one lazy tongs to the other. The swinging movement of which the said suspended lifting bars are, in this construction, capable, is, of course, as a reference to the said figures 130 will make manifest, such as to prevent any

possible travel of the lifting bars out of the radial axial planes of the die arms.

The Justifiers.

5 In the form of apparatus represented in the drawings, the end tier of die arms on each side of the machine, instead of being equipped with type dies, carries justifying blanks R, which, in connection with their spreading bars, as hereinafter explained, are devices for justifying or spreading out to a given breadth a line of composed type dies. The two tiers of die arms which are respectively provided with these justifying blanks on the 10 lowest or lowermost tiers respectively of the right and left hand series, are disposed upon opposite sides of the transverse central vertical plane of the machine, and are each controlled by a key and each of the same construction, relative disposition, and mode of operation as the tiers which are provided with the type dies.

In the use of a machine the operator, in composing a line of type dies, brings into 25 play a die arm provided with a justifying blank whenever he has finished the composition of a particular word, so that the said justifying blank is deposited in the composition line between the type die which bears 30 the last letter of a particular word and the type die which bears the first letter of the following word.

The justifying blank R, Figs. 1, 16, 18, 24, 25, 26, and 27, is itself a blank type-die, or a 35 housing so to speak, for carrying and depositing in the composition line, between particular character type dies, a tapering or wedge like bar, called a spreading bar r, which is so connected with the justifying blank as to 40 have a side for side movement with respect thereto, and is the immediate instrumentality for spreading apart or justifying the type dies which constitute a composed line.

The justifying blanks of the respective two 45 end tiers are respectively, as regards their attachment to the said two tiers of die arms, right and left handed blanks, as a reference to Figs. 15 and 16 will indicate, and the spreading bars which the said two sets respectively 50 carry are, by sets, respectively applied so as to wedge in from the right and from the left hand sides.

Each justifying blank of the respective right and left hand tiers thereof, essentially 55 corresponds in outline, when viewed from the front, with the outline of the respective right and left handed type dies, that is to say it is a cross head r² preferably provided with a circular slotted lip r³ for the attachment of 60 the knob k² of the die arm, and with a leg r⁴ corresponding with the leg of the type dies. The cross head, however, is longer than the cross head of a type die, and is provided longitudinally, that is to say in the direction of 65 the length of the said cross head, as to one of its faces with a dove tailed groove r⁵. The

spreading bar r is a bar of suitable length provided at its outer end with a turned down head r⁶. The taper of this bar is apparent from above or below but not from the front 70 or rear. The back face of this bar is also provided with a tongued web r⁷ by which the said spreading bar is adapted to travel in the direction of its own length, or side for side, through the dove-tailed groove r⁵ of the justifying blank R. The fit of the tongued web in the groove is exact. When a justifying blank has been deposited in the composition line, the spreading bar occupies a horizontal position about correspondent with the plane 80 of the surface of the base plate of the machine, and its turned down head r⁶ drops in the space or slot between the pushing rib s and the pulling rib s' of a follower S, the advance of which, through its pushing rib, occasions the pushing in of the spreading bar through its groove in the justifying blank to the position represented in Fig. 26, so as to cause the wedging apart of the type dies,— and the retreat of which, through its pulling 90 rib, occasions the withdrawing of the said spreading bar to the position of its normal set with respect to the justifying blank, or that set which it is indicated as having assumed in Figs. 24 and 25, and which it occupies when the justifying blank is lifted with its die arm and is at rest in its elevated position. This retreat of the follower and the retraction of the spreading bar is, of course, necessary before the bar is lifted into position to be again deposited, as, were a justifying blank deposited with its spreading bar pushed into its full extent, the effect of the tapering form of the bar for the spreading apart of the type dies would be lost.

As stated there are right and left handed sets of justifying blanks, and there are, as hereinafter explained, two slotted followers which respectively operate upon the respective sets of justifying blanks.

The spreading bar and justifying blank together form the justifying contrivance proper, and when I hereinafter in the claims speak of justifying blanks, justifying contrivances, or justifiers, I include both blank and bar and, when the sense requires it, means for operating the bars.

The Deflector.

T, Figs. 2, 9, 10, 11, 13, 14, 15, 19, 20, 21, and 48, is what I call the traveling deflector, the same being a block, preferably of metal, having an inclined face t which is adapted to deflect a type die or justifying blank which has almost completed its descent to the composition line into said composition line, and thereby to secure the accurate collocation of the said type dies and blanks as they are selected and deposited, and to obviate the possibility of a descending type die or blank dropping on top of the type die or blank which happens to have been last previously deposited. The set

of the die arms is such that the type dies and justifying blanks in their descent encounter the inclined face of the said deflector.

The deflector is conveniently suspended, or supported so to speak, by the suspensory rods t' from the rear segmental plate N' of the key board; and when the machine is at rest it occupies with respect to the composition line the position represented in Figs. 9, 10, and 14. The inclined face t of the deflector, which is the face the type dies and blanks encounter in their descent, is turned to the rear of the machine.

The first advance of the key board occasions a corresponding outward movement, or coextensive advance, of the deflector along the composition line; such advance taking place before the die arm released by the key which occasions the advance of the key board, makes its descent; and, upon each subsequent advance of the key board, the deflector makes a corresponding advance, so as to present just ahead of each subsequently descending type die or justifier blank, as represented in Figs. 15 and 20. When the entire line of dies has been composed, the deflector will have traveled to the position represented in Fig. 21, and will then serve as one of the abutments at the end of the composed line of dies, of which line the fixed inclined plate t^2 is the other abutment,—the two abutments serving to resist the spreading thrust of the spreading bars and to insure the end for end compacting of the composed line.

The traveling deflector is provided with a leg t^3 , corresponding in side for side dimensions with the leg of the type dies and justifying blanks, and this leg is included between and engaged by the clamping jaws, which are conveniently constructed and operated in the following manner.

The Clamping-Jaws.

After a given line of type dies has been composed or set up along the composition line, the right and left handed dies which compose it will not be aligned in the direction of the length of the line, but will stand apart a slight distance as already explained, and as represented in Fig. 17. It, therefore, becomes essential to align, or gather together into the same longitudinal line, the said deposited type dies and justifying blanks, and this I accomplish by a pair of curved clamping jaws U U' , Figs. 1, 2, 7, 8, 9, 10, 11, 13, 14, 15, 16, 17, 18, 19, 22, and 23, which are the aligning instrumentalities, which conveniently have about the same radius of curvature as that of the cylindriform table, and the biting faces u u' of which are straight and adapted to engage against the legs of the type dies and justifying blanks and to play through the central longitudinal broad opening or slot a^2 , which I term the clamp slot, in the base plate. Each of these jaws is formed with a pair of curved arms u^3 u^4 , which are mounted, by means of hubs u^5 u^6 , upon the plunger shaft

G as an axis, which shaft, as already stated, is housed in depending bearings below the base plate in the frame work. The normal set of these jaws is apart, as shown in Figs. 7 and 16, and between them and in the clamp slot a^2 of the base plate is the open space or area, the central transverse portion of which is the composition line, into which the legs 75 of the type dies and justifying blanks are deposited. The devices by which I cause the closing together of these jaws upon the said legs of the type dies, are a couple of pair of cam faced hub heels u^7 u^8 , Figs. 1, 2, 7, 8, 9, 80 and 10, which are connected with or spring from the hubs of the clamping jaws. As these hub heels and the contrivances which actuate them, as well as the devices which occasion the advance and retreat of the followers for moving the spreading bars, are doubled—that is to say, one set of each of the operative parts arranged in front and a corresponding set to the rear of the cylindriform table,—I will for simplicity describe but 90 a single set, or that in front.

The normal set of the hub heels when the clamping jaws are spread, is together, the said heels being so constructed that their curved or cam faces u^9 u^{10} face each other and embrace between them a double ended heel-trip V mounted upon the master shaft H . The master shaft is prolonged beyond its bearings to the front of the base plate, and is equipped with a twisting handle h . When this handle 100 is grasped, and sufficient rotation through it imparted to the master shaft, the heel-trip is rotated from the position which it is shown as occupying in Fig. 7 to that shown in Fig. 8; and, as the extremities of the said heel 105 trip work against the cam faces of the respective heel hubs, the latter are by the said rotation spread apart to the position shown in Fig. 8. Now as the hub heel u^8 is connected with the arm u^4 of the clamping jaw U' , and the hub heel u^7 connected with the arm u^3 of the clamping jaw U , it is obvious that the spreading apart of the said hub heels causes the approach of the said clamping jaws.

As each clamping jaw is provided with two 115 curved arms which straddle the curved face of the table, and as each of these arms is provided with a hub and each of said hubs with a hub heel, and as the master shaft extends completely across the table and is provided 120 with two heel trips which respectively operate upon respective pairs of hub heels, it is obvious that the force applied to cause the approach of the jaws is evenly distributed upon the curved arms and the jaws which 125 they carry.

The Followers.

After the jaws have been closed together so as to align the composed line of type dies and justifying blanks, it is necessary to effect the justifying, or longitudinal spread, of the respective type-dies and justifying blanks which form such line, and this, as already

stated, is accomplished by driving in the spreading bars of the justifying blanks. This driving in is accomplished by the action of the followers S, Figs. 1, 2, 7, 8, 9, 10, 11, 14, 5 15, 16, 18, 19, and 20, which are of substantially the form shown in the drawings and provided respectively with transverse ribs s^2 s^3 , designated respectively as pushing and pulling ribs because operating for such actions upon the turned down heads of the spreading bars, which bars are disposed within the clamp slot of the base plate beyond on each side and above the clamping jaws.

The followers are provided with suitably 15 forked or curved carrying arms s^2 s^3 , respectively connected with traveling guides s^4 s^5 , which latter are housed to slide in guide ways a^3 a^4 , slotted through the base plate on each side of and in parallelism with the clamp slot. 20 As each of the followers has a pair of carrying arms which are respectively connected with two separate traveling guides, it is obvious that there are in all four guides which, by twos, travel in the respective guide ways 25 and are connected with the arms of the opposite followers. Upon the master shaft are also mounted two double cranks h^2 h^3 , Figs. 1, 2, 7, 8, 9, and 10, which are respectively, by means of the links h^4 h^5 , linked with the traveling guides, and which serve through said links to limit the throw of the respective pairs of traveling guides which latter, as stated, are connected with and control the movement of the followers. The normal set of the double 35 cranks upon the master shaft is represented in Fig. 7, in which position the arms of the crank are in line with the links and the traveling guides and followers spread apart. When the master shaft is rotated so as to 40 cause the approach of the clamping jaws, the two double cranks are thrown into the position shown in Fig. 8, and the traveling guides and followers drawn together as shown in Fig. 18. The mounting of the heel-trips with 45 respect to the mounting of the double cranks upon the master shaft is such that the hub heels are spread apart and the clamping jaws brought together at the same time that the double cranks are rotated to cause the mutual 50 approach of the two followers, but the clamping of the jaws upon the dies and justifying blanks is completed before the completion of the mutual approach of the followers for the following reasons: As the slot e^6 in the 55 follower, or space which divides the pushing and pulling ribs thereof, is of considerable breadth, and as the turned down head of the spreading bar in the deposit of the justifying blank is caused to lie closer to the pulling rib 60 than to the pushing rib, as shown in Fig. 16, it is obvious that the jaws will have completed their approach during the period in which the followers have advanced sufficiently to bring their pushing ribs into contact with the heads 65 of the spreading bars, and that the completion of such mutual advance of the said followers as is necessary to cause the justifying

of the clamped line of dies, will therefore take place after the clamping jaws have ceased to move.

The action upon a reversal of the twisting handle of the master shaft is the reverse of the above, the followers spreading apart and retracting the spreading bars while the type dies and the justifying blanks of said bars 75 are still retained between the clamping jaws, and the clamping jaws spreading after the above retraction has been accomplished.

The Gate.

When the type dies and justifying blanks have been aligned and the spreading bars advanced to duty, the composed line is both aligned and justified, and the next operation is to bring down upon the cross heads of the dies and justifying blanks the gate E, which when brought down and held fixedly upon said cross heads serves as an abutment or resisting medium against the upward thrust of a plunger beneath the matrix, which plunger 90 operates to force the substance of the upper surface of the matrix into the outstanding characters which the type dies bear upon the under faces of their legs. These results I accomplish in the following manner: E, Figs. 2, 95 9, 10, 11, 12, 13, and 18, as stated, is a vertically disposed gate adapted to travel in ways d^2 d^3 in gate standards D D' erected from the base plate. The gate is laterally provided with gate pins g^2 g^3 which extend through vertical slots d^2 d^3 in the standards, and exterior to said standards are connected with the upper extremities of a pair of connecting rods W W' which respectively pass down through the slotted guide ways a^3 a^4 in the bed plate, 105 and are connected with crank levers g^1 g^2 mounted upon the plunger shaft. The plunger shaft extends forward beyond its depending bearings, and as to its projecting extremity is equipped with a hand lever g^x , by 110 means of which the rotation of the shaft may be accomplished. Normally this hand lever occupies the position represented in full lines in Fig. 1. Now it is obvious that a deflection of said lever in the direction of the arrow upon its handle into the position represented in dotted lines in said Fig. 1, will occasion such a partial revolution of the plunger shaft as will throw its crank levers from the vertical upper position which they are represented 115 as occupying in Figs. 7 and 10, to the position which they are represented as occupying in Fig. 8, with the result that, through the medium of the connecting rods, the gate will have been brought down upon the cross heads 120 of the dies into the position shown in Fig. 18, in which position the lower edge of the gate rests upon each one of the dies and serves to resist any upward thrust against said dies.

A reference to Figs. 1, 7, and 10, of the drawings will show that the connecting rods near their lower extremities are provided with hook-shaped recesses w^1 w^2 from the under faces of which run or extend curved steps w^2 w^3 . The

office of these recesses and the steps which form the approaches to them, is to permit of the taking of the connecting rods, after the throw of the hand lever and of the crank lever 5 vers of the plunger shaft, in under the plunger shaft as shown in Fig. 8, the intention being to bind the gate down rigidly to the plunger shaft so as to avoid any possibility of the lift of the gate, and to strengthen the set of 10 the gate as an abutment against the thrust of the plunger. The steps serve to measurably secure the above result before the complete seating of the connecting rods by their recesses upon the said plunger shaft.

15. The gate is provided with two hook clamps g^3 g^3 , Figs. 9, 10, 11, 12, and 13, which, when the gate descends, by their slightly angled edges take tight hold upon laterally extending and preferably correspondingly angled 20 ears u^x u^x (Figs. 13, 14, 15, and 18), upon the clamping jaws in proximity to the biting faces thereof, and thereby serve, until the gate is lifted, to fixedly retain together against any possible separation the biting faces of said 25 clamping jaws.

Y, Figs. 9, 10, 12, 19, and 21, is a depending wedge upon one side of the gate, which is adapted when the gate descends to encounter the oppositely tapering back t^4 of the deflector T, and press the latter, as indicated in Fig. 21, tightly in against the dies and blanks, while at the same time forming a rigid back against which the deflector itself abuts, and serving also to prevent the spreading bars of 35 the justifiers from springing out said deflector beyond its proper position.

The Plunger.

The plunger shaft, at a point between the 40 two central depending bearings, is provided with a cam surface g^2 , which in the normal set of the plunger shaft is beneath the same, as shown in Figs. 10 and 11.

X is the plunger, a vertically disposed plate 45 corresponding somewhat to the gate, housed in ways f formed in the opposing faces of the two central depending bearings, and adapted when forced vertically upward to pass through a plunger slot x formed transversely across 50 the table.

The weight of the plunger is such that in the normal set of the plunger shaft it rests upon it and occupies the position represented, for instance, in Figs. 10, 11, and 16. In this 55 position it does not interfere with the travel of the matrix upon the table. Upon the rotation of the shaft, the cam surface thereof encounters the said plunger and forces it up through the slot in the table to above the surface 60 of said table, as shown in Fig. 18, and by such means causes it to force the matrix into the dies. This action takes place after the gate has descended, and is occasioned by the throw of the hand lever g^x of the plunger 65 shaft. The reverse throw of the said hand lever occasions first the reverse travel of the

cam surface on the plunger shaft, so that the plunger drops, and then, through the crank levers and connecting rods, the elevation of the gate.

In the operation of the machine the twist of the twisting handle on the master shaft is first resorted to, so as to operate the jaws and followers to align and justify the dies of a composed line, and the hand lever is then deflected so as to first bring down the gate and then force up the plunger to impress the matrix with the characters of said composed line.

After the matrix has been impressed, the hand lever is first thrown back, so as to cause the drop of the plunger and the lift of the gate, and the twisting handle is then given a reverse twist so as to bring about the retraction of the spreading bars and the retreat of the clamping jaws.

The Matrix Feed.

The matrix J is of the width of the cylindrical table, and is adapted to be fed from left to right upon said table by feed mechanism 90 shown in Figs. 1, 7, 8, 11, 22, and 23, which is of the following construction:

Z is a shaft, transversely journaled beneath the bed of the table, which is equipped with two feed wheels $z z$ the peripheries of which 95 extend up, through suitably disposed openings upon each side of the table, level with the carrying surface thereof. The shaft projects through the front side web of the table, and beyond such web is equipped with a fixed 100 ratchet wheel z' , about and inclosing which, upon said shaft as an axis, hangs a swinging trip z^2 , which is provided with a pawl z^3 set to engage the teeth of the ratchet wheel. Suitably housed, preferably in the same vertical planes with and immediately above the feed wheels $z z'$, are two idler friction rolls $z^4 z^4$ 105 which are set to slightly squeeze the lateral edges of the matrix against the feed wheels.

The swinging arm z^3 is, in the set of the 110 parts, adapted to be encountered by a tappet z^5 connected with one of the arms u^4 of one of the clamping jaws U', so that, as the said jaw is thrown in for engagement with the dies, the tappet encounters the arm of the 115 swinging trip and causes the deflection of the latter from the position represented in full lines in Fig. 22 to that represented in dotted lines, thereby occasioning, through the engagement of the pawl with the ratchet wheel 120 z' such sufficient rotation of the shaft Z and of its feed wheels $z z$ as, in connection with the bite of the friction rolls, to occasion a predetermined advance of the matrix, to an extent sufficient, for instance, to bring an unimpressed portion thereof succeeding an impressed portion on top of the plunger and in position to be forced into the composed line of dies. Upon the retreat of the clamping 125 jaws the swinging trip gravitates to its first 130 position, its pawl lifting over a sufficient number of the teeth of the ratchet to occasion,

upon the next deflection of the trip, a still further and corresponding advance of the matrix.

As a reference to Figs. 11 and 14 will show, 5 the upper portion of the table is bounded at front and back by the walls of the clamp slot a^2 in the base plate, the said walls serving to keep the matrix in place. The curved arms of the clamping jaws also subserve a similar 10 purpose.

Although the matrix is bent to the curvature of the table in its travel over it, yet, when the impression of the composed line of 15 dies is made in the matrix by the lift of the plunger, as already explained, that portion of the matrix which is carried up and supported upon the acting face of the plunger is level and not curved, because the acting face of the plunger is itself level, as a reference 20 to Fig. 18 will indicate.

Recapitulation of the Operation.

Having now described the construction of the parts which in their assembled relationship compose a good form of machine embodying my invention, and having, as far as possible, described the operation of each of the said parts at the same time, it is unnecessary, except briefly, to recapitulate the 30 operation of the machine.

First, assume all of the die arms of all of the tiers elevated, the distributing mechanism at rest upon the frame plates, the key-board frame work pushed back against the 35 front frame plates to the extent of its inward movement, the clamping jaws and followers for operating the justifying devices spread apart, the gate elevated and the plunger depressed. In other words, first assume all of 40 the parts in the positions which they are represented as occupying in Figs. 1 and 2, or the machine at rest and ready for action. In the foregoing position, as already explained, all of the trigger lugs are to the rear of the rear- 45 most triggers in all of the die arm cases, and the deflector is in against the inclined fixed plate t^2 of the base plate, as shown in Fig. 9.

Now, in order to permit the depositing in the 50 composition line of a type die with which the desired line of dies is to be commenced, it is necessary, first, to advance the key board a sufficient distance to bring all of the trigger lugs face to face with the triggers controlling the rearmost die arms of all of the tiers, so. 55 that a die arm from any one of the tiers desired may be deposited, and, second, to advance the deflector from the fixed inclined plate a predetermined distance correspondent with the breadth of the die to be deposited.

Both of the foregoing results are accomplished by the depression of any key in the key board, occasioning, as already fully explained, through the instrumentality of the ratchet finger connected with said key, the 60 ratchet frame, and the gearing connected with said ratchet frame, a predetermined advance of the key board. It is, therefore, obvious

that any particular key which happens to be first struck, will not only operate to occasion the predetermined requisite advance of the 70 key board and of the deflector, but also to occasion the deposit at the proper point of a type die corresponding to the character with which the key is marked. After the first key has been struck, the key board and deflector 75 advanced, and the required type die deposited, the key will be, in a manner already explained, returned to its normal set, and the ratchet frame will likewise be returned, so that all the parts will be in readiness for the de- 80 pression of a succeeding key controlling a tier containing a die arm and a die of the character next required for deposit. The striking then of a succeeding key, as in the case of the key first considered, will occasion such a further 85 advance of the key board frame work as will bring the trigger lug of said key in front of a trigger controlling a die arm which is, with respect to transverse disposition in its case, the proper arm to be deposited in the then 90 newly opened space in the composition line between the deflector and the last deposited type die.

The above described operation is to be repeated with subsequently selected keys, until 95 a sufficient number of type dies has been deposited to form a composed line of the required breadth.

Of course it is to be understood that between the composed words, the keys controlling the justifier blanks are to be struck, that wherever a space is desired in the line the justifying blanks are to be called into play, and that in speaking of a composed line of type dies I refer to a line which is composed 105 of both justifying blanks and type dies proper.

After a sufficient number of type dies to compose a line has been deposited as already described, the master shaft is to be rotated so as to occasion both the action of the clamping jaws for the aligning of the dies of the composed line and the operation of the matrix feed, and the action of the followers for the driving in of the spreading bars for the justification of said line; after which rotation 115 of the master shaft the plunger shaft is to be rotated so as to occasion the bringing down of the gate upon the justified and aligned line of type dies, and the elevation of the plunger against the matrix to secure the impression of the latter by the dies, and also incidentally to secure, as fully explained, the clamping together of the jaws by the hook clamps which the gate carries and the wedging up of the deflector against the end of the 120 composed line of dies. After the matrix has been impressed, the plunger shaft is to be reversely rotated so as to cause the retreat of the plunger and the lift of the gate. The master shaft also is then to be reversely rotated to occasion the retreat of the followers and the retraction of the spreading bars to their normal set with respect to the justifying 130 blanks which carry them, and to likewise oc-

5 occasion the subsequent retreat of the jaws, whereby moreover the matrix feed is also released to automatically resume its set for the next advance of the matrix. The distributor is then to be elevated so as to occasion the simultaneous elevation and re-engagement by their triggers of all of the die arms dropped for the composition of the line of type dies last impressed, after which the distributor is to be permitted to resume its normal set. The pivoted pawl of the ratchet frame is then to be lifted and the key board frame work pushed or pulled in by hand, or by the operation of a spring or counterweight, 15 to the full extent of its inward movement, whereupon the machine is ready to be again operated, in the manner already described for the composition and impression of a succeeding line in the matrix.

20 Having now described both the construction and operation of such devices as conveniently embody my invention, it is proper to explain that in the event of the accidental depression of the wrong key and the descent 25 of the wrong die arm an occurrence often instantly discovered, the arm in question can be raised by itself by hand, and the proper arm be, by the touching of its own key, deposited in the place of the arm wrongly deposited and lifted, the pivoted pawl of the 30 ratchet frame being at the same time lifted and held up so as to prevent the advance of the key board. Should, however, the mistake not be discovered until the line has been entirely composed, an inspection of the facsimiles of the characters on the upper surface of the dies will indicate to the operator the error before the impression is made in the matrix, and the entire line can be at once distributed and re-composed.

35 I have hereinbefore, with some minuteness, described specific mechanisms for causing the approach and recession of the clamping jaws and of the followers for operating the justifying contrivances, as well as specific mechanisms for causing the depression and lift of the gate and the elevation and depression of the plunger. I do not, however, confine myself to the specific means, which I have represented and described as convenient, for 40 occasioning the relative operation of the said jaws, followers, gate, and plunger, as it will be obvious to any skilled mechanic that other mechanisms can, with perhaps equal utility, 45 be substituted for the same purposes in the stead of the specific mechanisms which I have described. It is, however, essential that the jaws or contrivances for aligning a composed line of dies, the followers or devices for operating the justifying contrivances, the gate or contrivance for holding down the composed and aligned line of dies, and the plunger or device for forcing the matrix against the dies, should, either in the form which I have 50 represented and described them, or in equivalent forms, be present as operating instrumentalities of my machine as an organized

whole. It is also obvious that the table or bed upon which the matrix rests and travels need not necessarily be cylindriform; that it 70 would also be possible, although not advisable, to dispense with the deflector which is carried by the key board, or to mount the said deflector independently of the key board and occasion its gradual predetermined advance 75 by other means than said key board; that the specific mechanism for occasioning the predetermined advance of the key board upon the touching of any key therein might be modified, although the provision of mechanism by 80 which, upon the depression of any key, the key board must advance, is essential to the successful operation of my machine; that, as already stated, modifications in the form of the die arm cases, of the distributor, and of the 85 means for elevating the latter, may be resorted to; and that the matrix feed may be modified both in construction and mode of operation. In other words, the merely mechanical details of the machine may, of course, be varied 90 without departing from the invention, which consists, as hereinafter recited in the claims, in the combination in an organized machine of certain co-operating instrumentalities which, in their connected relationship, effectuate results hereinbefore set forth, and also in the provision or construction of certain instrumentalities themselves.

Having thus described my invention, I claim and desire to secure by Letters Patent 100 of the United States—

1. In a machine for making stereotype matrices, the combination with a longitudinally slotted die arm, of a type die removably connected therewith, substantially as described. 105

2. In a machine for making stereotype matrices, the combination with a die arm composed of a wire, rod, or piece of metal, which forms an inverted **U** between the legs of which is a longitudinally disposed slot or open 110 space, of a removably applied type die connected with one of the legs, substantially as described.

3. As a new article of manufacture, a die arm for a machine for making stereotype 115 matrices, composed of a wire, rod, or piece of metal, which forms an inverted **U**, between the legs of which is a longitudinally disposed slot or open space, and one of the legs of which is provided with an off-set. 120

4. As a new article of manufacture, a die arm for a machine for making stereotype matrices, composed of a wire, rod, or piece of metal, which forms an inverted **U**, between the legs of which is a longitudinally disposed 125 slot or open space, and one of the legs of which is provided with a flattened or spring-like extension.

5. As a new article of manufacture, a die arm for a machine for making stereotype 130 matrices composed of a wire, rod, or piece of metal, which forms an inverted **U**, between the legs of which is a longitudinally disposed slot or open space, and one of the legs of which

is provided with a flattened or spring-like extension terminating in a knob or enlargement.

6. As a new article of manufacture, a die arm for a machine for making stereotype matrices composed of a wire, rod, or piece of metal, which forms an inverted U, between the legs of which is a longitudinally disposed slot or open space, and one of the legs of which is provided with an off-set, and the other leg with a flattened or spring-like extension.

7. In a machine for making stereotype matrices, a type die provided with a slot and an enlargement thereof, in combination with a die arm which is provided with an extension adapted to said slot and with an enlargement adapted to the enlargement of said slot, substantially as set forth.

8. As a new article of manufacture, a type die, for a machine for making stereotype matrices, having a transverse cross head and a depending leg upon the under surface of which latter is applied the type or character die, and the cross head of which is provided with a slot communicating with a transverse enlargement.

9. In combination with a type die composed of a cross head and a depending leg and provided as to its cross head with a slot, a die-arm having a spring-like extension adapted to said slot.

10. In combination with a type die composed of a cross head and a depending leg and provided as to its cross head with a slot having an enlargement,—a die arm having a spring like extension provided with an enlargement adapted to the slot in said type die, substantially as set forth.

11. In a machine of the class above recited, in combination with a die arm, a removably applied justifying blank having a depending leg and provided with a tapering spreading bar, substantially as shown and described and for the purposes set forth.

12. In a machine for making stereotype matrices, the combination with a die arm, of a removably applied justifying blank having a depending leg and a transverse cross head provided with a dove tailed groove, and of a tapering spreading bar carried by the blank and adapted to have a movement within the dove-tailed groove, substantially as shown and described and for the purposes set forth.

13. In a machine of the class above recited, the combination of a composed line of type dies and justifying devices, a fixed plate at one extremity of said line, a deflecting plate at the opposite extremity of said line, a slotted base plate or other fixture for the fixed plate and deflector to abut against, and means essentially such as described for operating the justifying devices so as to occasion the spreading of the type dies laterally against both the fixed plate and the deflector, substantially as shown and described and for the purposes set forth.

14. In a machine of the class above recited, the combination, to form a series of die arm

cases, of a series of pairs of sectoral end plates connected together by pairs by transverse diaphragms, with frame plates for connecting together the sectoral end plates, substantially as shown and described and for the purposes set forth.

15. In a machine of the class above recited, the combination to form a die arm case of sectoral end plates, a transverse groove-provided diaphragm, and a transverse groove-provided bottom plate, substantially as shown and described and for the purposes set forth.

16. In a machine of the class above recited, the combination to form a die arm case, of sectoral end plates, a transverse groove-provided diaphragm, a transverse groove-provided bottom plate, and a transverse bar for supporting trigger springs, substantially as shown and described and for the purposes set forth.

17. In combination: a series of die arm cases each composed of two sectoral end plates, a transverse groove provided diaphragm, a transverse groove-provided bottom plate, and a transverse bar for supporting trigger springs;—means, essentially such as set forth, for maintaining said series assembled in an arc shaped relationship;—and a row or tier of inverted U-shaped die arms contained in each die arm case, and which straddle the diaphragms, substantially as set forth.

18. In a machine of the class above recited, the combination of a die arm case provided with a radially grooved transverse diaphragm and a groove provided transverse bottom plate,—a series of die arms adapted to the said grooves and having a movement therein, a series of pivoted triggers,—and a series of trigger springs controlling said triggers, substantially as shown and described and for the purposes set forth.

19. In a machine of the class above recited, the combination of a die arm case, a sheath or bearing therein for a key stem, and a key stem, substantially as shown and described and for the purposes set forth.

20. In a machine of the class above recited, the combination of a die arm case, and a series of triggers pivoted in grooves formed therein and provided with stops for engagement against the ribs between the grooves, substantially as shown and described and for the purposes set forth.

21. In a machine of the class above recited, in combination with the sectoral end plates connected together by a transverse diaphragm, a bottom plate provided with a series of grooves and with a slot, substantially as set forth.

22. In a machine of the class above recited, the combination of a series of radially disposed die arm cases having radial diaphragms or partitions, and a series of tiers of slotted or inverted U-shaped die arms through the slots of which the diaphragms pass, substantially as shown and described and for the purposes set forth.

23. In a machine of the class above recited,

the combination of a series of radially disposed die arm cases having radial diaphragms or partitions both of the faces of each of which are provided with grooves or ways for die arms, and a series of tiers of slotted inverted U-shaped or two-armed die arms which straddle the diaphragms and the arms of which are respectively entered in ways upon opposite sides of the diaphragms, substantially as shown and described and for the purposes set forth.

24. In a machine of the class above recited, the combination of the table, means essentially such as described for feeding the matrix, and the clamping jaws which overhang the table, substantially as shown and described and for the purposes set forth.

25. In a machine of the class above recited, in combination with a die arm case having a groove-provided diaphragm provided with radial ribs, a series of triggers pivoted between the said radial ribs, and a comb spring plate the springs of which are engaged with the triggers, substantially as set forth.

26. In combination with a series of die arm cases, a series of tiers of longitudinally slotted die arms contained therein, a series of levers connected together after the manner of a lazy tongs and provided with lifting bars which respectively pass through the slots of all the die arms of all of the tiers, and means, substantially as described, for occasioning the elevation of the said connected levers, substantially as set forth.

35 27. The combination to form a distributing apparatus for the die arms of a machine for making stereotype matrices, of a series of levers connected together after the manner of a lazy tongs, lifting bars connected with said levers, sleeves likewise connected with said levers and traveling upon radially disposed frame posts in the frame work of the machine, and a frame work containing the frame posts, substantially as described.

45 28. In combination with frame plates having an arc shaped top substantially of the construction and for the purposes set forth, the lazy tongs distributer which when at rest rests upon said frame plates, and frame posts for guiding the distributer when raised, substantially as described.

29. In combination with two correspondingly arc-shaped lazy tongs connected together by a series of lifting bars and having a radial movement in the frame work, a series 55 of tiers of slotted die arms through the slots of all the die arms of given series of which given lifting bars pass, and means, substantially such as are described, for securing the

60 radial movement of said connected lazy tongs so as to occasion the elevation of the die arms, substantially as set forth.

30. In a machine for making stereotype matrices, in combination with a series of die 65 arm cases, a series of die arms, a lazy tongs distributer, and cords connected therewith and passing over suitably supported fixed

pulleys for securing the elevation of said distributor, substantially as set forth.

31. In combination with an arc-shaped lazy 70 tongs distributer composed of a series of connected levers the three pivotal points of each of which levers lie in the arc of a circle, a series of die arm cases assembled in arc-shaped relationship, and a series of radial frame 75 posts in connection with which the said distributor moves, substantially as set forth.

32. As a new article of manufacture, two connected arc-shaped lazy tongs, provided at given distances with sleeves to which certain 80 of the levers composing said connected tongs are pivoted, and also provided with transverse lifting bars connecting the central pivotal points of corresponding crossing levers in the respective tongs, substantially as set forth. 85

33. In combination with a frame work composed of a base plate, frame plates, and radial frame posts essentially composing a supplemental frame work upon which are mounted pulleys,—a lazy tongs distributer having a 90 radial movement with respect to said frame posts, and cords connected with said distributor and passing over said pulleys, substantially as set forth.

34. In a machine of the class above recited, 95 the combination of the lazy tongs distributer, means as described for guiding the movement thereof, means as described for elevating the same, and the spring pulleys for drawing the same down, substantially as shown and described and for the purposes set forth.

35. In combination with a frame work composed essentially of a base plate, frame plates and radial frame posts, the lazy tongs distributer provided with sleeves which are fitted 105 to and travel upon the frame posts, and means as described for securing the lift of said sleeves with respect to said frame posts, substantially as set forth.

36. In a machine for making stereotype 110 matrices, the following elements in combination:—a series of die arm cases, a frame work for supporting the same, a key board having an in and out movement with respect to said cases, and supports upon which said key board 115 moves in and out, substantially as shown and described and for the purposes set forth.

37. In a machine for making stereotype 120 matrices, the following elements in combination:—a series of radially disposed die arm cases arranged in arc shaped relationship, a frame-work for supporting the same, a key board of arc shaped form, and supports for said key board upon which it has an in and out movement in parallelism with the die arm 125 cases, substantially as described.

38. The combination, in a machine for making stereotype matrices, of a fixed supporting frame containing die arm cases, a series of radially disposed tiers of die arms, a key board 130 frame work provided with a series of keys corresponding in number with the tiers of die arms, mechanism substantially such as is described for controlling the retention of the die

- arms in their cases, mechanism substantially such as described controlled by separate keys and adapted to release given die arms of the tiers, and automatic mechanism substantially 5 such as is described controlled alike by all of the keys and adapted upon the depression of any key to cause a predetermined movement of the key board, substantially as shown and described and for the purposes set forth.
- 10 39. In a machine of the class above recited, the combination of the slotted base plate, the frame work containing die arm cases and tiers of die arms, the movable key board, and the deflector connected and having movement 15 with said key board transversely with respect to the slot in the base plate, substantially as shown and described and for the purposes set forth.
- 10 40. In a machine for making stereotype 20 matrices, the following elements in combination:—a series of die arm cases contained in a fixed frame work, a series of tiers of die arms contained in the said cases, triggers for retaining all of the die arms in an elevated position, 25 a movable key board, a series of keys, corresponding in number with the series of tiers of die arms, contained in the key board and controlling the triggers which retain the die arms in their elevated position, and mechanism 30 essentially such as described common alike to all the keys whereby the depression of any key occasions an advance movement in the key board, substantially as set forth.
- 10 41. In a machine for making stereotype 35 matrices, the following elements in combination:—a supporting frame containing a series of radially disposed die arm cases, a series of tiers of die arms respectively contained in the cases, a series of triggers for maintaining the 40 die arms in their elevated positions, a key board frame work, a series of keys corresponding in number with the tiers of die arms and respectively provided with key stems which pass through the die arm cases and carry each 45 a lug for engagement with the triggers, and mechanism essentially such as described for occasioning the advance of the key board and its keys upon the depression of any key, substantially as described.
- 10 42. In a machine for making stereotype 50 matrices, the following instrumentalities in combination: a series of die arm cases, a frame work for supporting the same, a series of triggers in said cases, a series of die arms in said 55 cases, a movable key board, supports which sustain the key board in such relation to the die arm cases that it may have a movement in and out with respect thereto, a series of keys, a series of key stems passing through the die arm 60 cases and provided with a series of triggerlugs for controlling the drop of particular die arms, mechanism, substantially such as is described, common to all of the keys and actuated by any one of them for causing the predetermined 65 advance of the key board upon the depression of a key, and a distributer for simultaneously elevating all of the dropped die arms, substan-

tially as shown and described and for the purposes set forth.

43. In a machine for making stereotype 70 matrices, the following elements in combination: a series of die arm cases, a series of tiers of die arms provided with type dies, a key board provided with keys respectively operating in connection with particular tiers of 75 die arms and adapted to occasion the successive drop of selected die arms to form a composed line, means essentially such as described for occasioning the predetermined advance of the key board upon the depression of any key, 80 means essentially such as described for aligning the composed line of dies, means essentially such as described for fixedly holding down the composed line of dies, and means essentially such as described for forcing a matrix against the aligned and held down dies, substantially as shown and described and for the purposes set forth.

44. In a machine for making stereotype 90 matrices, the following elements in combination:—a series of die arm cases, a series of tiers of die arms provided with type dies, one or more tiers of die arms provided with justifying contrivances, a key board provided with keys respectively operating in connection 95 with particular tiers of die arms and adapted to occasion the successive drop of selected die arms to form a composed line, means essentially such as described for occasioning a predetermined advance of the key board upon 100 the depression of any key, means essentially such as described for aligning the composed line of dies, means essentially such as described for throwing into action the justifying contrivances, means essentially such as described for fixedly holding down the composed line of dies, and means essentially such as described for forcing the matrix against the aligned and held down dies, substantially as 105 shown and described and for the purposes set forth.

45. In a machine of the class above recited, the combination, with a frame work supporting die arm cases, of a key board frame, a series of key stems supported or mounted in 110 segmental or arc-shaped relationship therein and provided with keys, and boxings connected with the frame by means of which the frame and its connected keys and stems are adapted together to be moved, substantially 115 as shown and described and for the purposes set forth.

46. In a machine of the class above recited, in combination with a key board frame composed of segmental plates connected together 120 by boxings, fixed studs upon which said boxings are mounted for movement, and a frame work for supporting said fixed studs, substantially as shown and described and for the purposes specified.

47. In a machine of the class above recited, the combination of a key board frame, supports upon which said frame is mounted for movement, key stems provided with keys, a 130

5 ratchet or abutment frame, ratchet fingers upon the key stems for imparting a movement to the ratchet frame upon the touching of any key, and means essentially such as described which through an impulse imparted to the ratchet frame by a key occasions a movement of the key board upon its supports, substantially as shown and described and for the purposes set forth.

10 48. In combination, a series of die arm cases disposed in an arc and each containing a tier of die arms, a key board frame, supports upon which said frame is mounted for movement, a series of key stems provided with keys and 15 ratchet fingers, a ratchet frame provided with abutments, and means, essentially such as described, for occasioning the advance of the key board and the consequent movement of the ratchet frame upon the movement of any key, 20 substantially as set forth.

49. In a machine of the class above recited, the combination of a key board frame, a series of key stems provided with keys and with ratchet fingers of varying length, and a ratchet 25 frame provided with abutments of varying form and extent, substantially as set forth.

50. In a machine of the class above recited, the combination of the key board frame provided with boxings, keys carried by the said 30 frame, the ratchet frame, the pawl connected therewith, the ratchet shaft housed in the key board frame, the ratchet wheel, the toothed spur wheels, the studs or supports for the boxings of the key board frame, and the racks 35 upon said studs, substantially as shown and described and for the purposes set forth.

51. In a machine of the class above recited, the combination of the ratchet frame, the spring controlled, toothed pawl, the ratchet 40 wheel, the shaft upon which said wheel is mounted, and means, substantially such as are described, for occasioning a movement of the ratchet frame, substantially as shown and described and for the purposes specified.

45 52. In a machine of the class above recited, the combination of the key board frame, the key stems provided with keys and ratchet fingers, the ratchet frame, and the spring for returning the ratchet frame, substantially as 50 shown and described and for the purposes specified.

53. In a machine for making stereotype matrices, the following elements in combination:—a series of die arm cases, a series of tiers 55 of die arms composed respectively of different numbers of die arms, a key board frame, a series of key stems connected therewith provided with keys and trigger lugs, and mechanism essentially such as described for occasioning varying predetermined advances of the key board frame upon the touch of different keys, substantially as shown and described and for the purposes set forth.

54. In a machine for making stereotype 60 matrices, the following elements in combination:—a series of die arm cases, a series of tiers of die arms composed respectively of differ-

ent numbers of die arms, a key board frame, a series of key stems connected therewith provided with keys and trigger lugs and with 70 ratchet fingers of varying length, a ratchet frame provided with abutments of varying form and extent adapted to be engaged and moved by given ratchet fingers, and means essentially such as described for communicating a predetermined movement of the ratchet frame to the key board so as to occasion a predetermined varying advance thereof, substantially as shown and described and for the purposes set forth. 75

55. In a machine for making stereotype matrices, the following elements in combination: a series of die arm cases, a frame work for the same, a key board having a separate key for each separate row or tier of die arms 85 and having an in and out movement with respect to said cases, and keys the depression of any one of which controls the advance of the key board, substantially as described.

56. In a machine for making stereotype 90 matrices, the following elements in combination: a composed line of type dies, a slotted base plate within the slot of which the said line is composed, a table for a traveling matrix below the base plate, clamping jaws for 95 aligning the composed line of dies, a gate for holding down said composed line, a plunger for lifting the matrix from the table and forcing it against the dies, and means essentially such as described for operating said jaws, 100 gate, and plunger, substantially as shown and described and for the purposes set forth.

57. In a machine for making stereotype matrices, the following elements in combination:—a composed line of type dies, a slotted 105 base plate within the slot of which the said line is composed, a table for a traveling matrix, clamping jaws for aligning the composed line of dies, a gate for holding down said composed line, a plunger for lifting the matrix 110 from the table and forcing it against the dies, automatic mechanism essentially such as described for occasioning a predetermined advance of the matrix, and means essentially such as described for operating said jaws, gate, 115 and plunger, substantially as shown and described and for the purposes set forth.

58. In a machine for making stereotype matrices, the following elements in combination:—a composed line of type dies and justifying blanks, a slotted base plate within the slot of which the said line is composed, a table for a traveling matrix, clamping jaws for aligning the composed line of dies, means essentially such as described for operating the 125 justifying contrivances, a gate for holding down said composed line, a plunger for lifting the matrix from the table and forcing it against the dies, and means essentially such as described for operating said jaws, gate, and 130 plunger, substantially as shown and described and for the purposes set forth.

59. In a machine for making stereotype matrices, the following elements in combina-

tion: a composed line of type dies and justifiers, a slotted base plate within the slots of which the said line is composed, a table for a traveling matrix, clamping jaws for aligning 5 the composed line of dies, followers for operating the justifiers, a gate for holding down said composed line, a plunger for lifting the matrix from the table and forcing it against the dies, a matrix feed, and means essentially 10 such as described for operating said followers, gate, plunger, and matrix feed, substantially as shown and described and for the purposes set forth.

60. In a machine of the class above recited, 15 the combination of an arc-shaped or semi-circular series of radially disposed die arm cases, a suitable frame work for supporting the same, and a series of tiers of die arms provided respectively with right and left handed 20 dies and, by such tiers, respectively disposed upon opposite sides of the center or vertical axis of the said series of tiers of die arm cases, substantially as shown and described and for the purposes set forth.

61. In a machine for making stereotype matrices, the following elements in combination: a semi-circular supporting frame work, a series of radially or approximately radially disposed die arm cases arranged upon both 30 sides of the central vertical radial plane of said frame work, a series of tiers of die arms contained in the right hand series of die arm cases respectively provided with right handed type dies, a series of tiers of die arms contained in the left hand series of die arm cases respectively provided with left handed type dies, jaws for aligning a composed line respectively of arbitrarily selected right and left handed type dies, a gate for holding down 40 said composed line of such selected dies which operates in the central radial plane of the frame work, a plunger for forcing up a matrix against said dies also operating in the said central radial plane, and means essentially 45 such as described for occasioning the operation of the aligning, holding down, and matrix impressing contrivances, substantially as shown and described and for the purposes set forth.

62. In a machine of the class above recited, 50 the combination of a series of radially disposed tiers of die arms, of which series those tiers the arms of which are provided with narrow letters are formed of a greater number 55 of die arms than the number of arms composing those tiers the arms of which are provided with broad letters, but all of the tiers of which series are of the same depth, substantially as shown and described and for the 60 purposes set forth.

63. In a machine of the class above recited, 65 the combination of a rotatable key stem in combination with a radially applied lever key, substantially as shown and described and for the purposes set forth.

64. In a machine of the class above recited, 70 the combination of an arc-shaped or seg-

mental key board with a series of rotatable key stems disposed in arc-shaped relationship and respectively provided with radially disposed lever keys which have a common inclination in the key bank but are adapted when depressed to clear each other, substantially as shown and described and for the purposes set forth.

65. In a matrix machine having a series of die arm cases containing each a row or tier of die arms, a movable key board having a separate key for each row or tier of die arms and which moves whenever a key is depressed, 75 substantially as set forth.

66. In a machine of the class above recited, the combination of the clamping jaws mounted through the medium of arms upon the plunger shaft, the plunger shaft, the cam faced hub heels connected with the arms of the jaws, the master shaft, the heel trips on said master shaft, and means essentially such as described for occasioning an intermittent oscillation or half revolution of said shaft, 85 substantially as shown and described and for the purposes specified.

67. In a machine of the class above recited, as a means for aligning and for holding down a composed line of type dies, two oppositely 90 moving clamping jaws adapted from both sides to engage and colligate the type dies, a gate above the type dies, and means essentially such as described for securing the mutual approach and retreat of the jaws and the 95 drop and lift of the gate, substantially as shown and described and for the purposes set forth.

68. In a machine of the class above recited, 100 as a means for holding down a composed line of type dies and for elevating a matrix to receive the impression thereof, the combination of the gate, the plunger, the connecting rods, the crank levers, the plunger shaft, and means essentially 105 such as described for rotating said plunger shaft, substantially as shown and described and for the purposes set forth.

69. In a machine of the class above recited, 110 the combination of the movable key board and the deflector, substantially as shown and described, and for the purposes set forth.

70. In a machine of the class above recited, 115 the combination of a slotted bed plate provided with a fixed plate upon one side of its slot, a composed line of type dies, a traveling deflector, a key board to which the deflector is connected and by the movement of which it is moved and placed against one end of the composed line of dies, a gate for holding down 120 said line of dies, and a wedge upon said gate for engaging the deflector, substantially as shown and described.

71. In a machine of the class above recited, 125 as a means for occasioning the advance and retreat of the followers, the combination of the double cranks, the links, and the master shaft, substantially as shown and described and for the purposes specified.

72. In a machine of the class above recited, the combination of a composed line of type dies, clamping jaws for aligning and a gate for holding down said dies, and hooked clamps 5 upon the gate for retaining together the jaws, substantially as shown and described and for the purposes set forth.

73. In a machine of the class above recited, the combination of the gate traveling in suitable standards, the connecting rods provided with hook-shaped recesses, the plunger shaft provided with crank levers connected with said connecting rods, the plunger upon said plunger shaft, and means essentially such as 15 described for occasioning a partial oscillation of the plunger shaft so as to occasion the depression of the gate, the elevation of the

plunger, and the seating of the connecting rods by their hook shaped recesses upon the plunger shaft, substantially as set forth. 20

74. In a machine of the class above recited, the combination of the slotted base plate and the traveling deflector having movement transversely with respect to the slot in the base plate, substantially as and for the purposes set forth. 25

In testimony whereof I have hereunto signed my name this 7th day of February, A. D. 1885.

JACOB RUPERTUS.

In presence of—

J. BONSALL TAYLOR,
JOHN K. RUPERTUS.
